UNITED STATES PATENT OFFICE.

EDWIN H. SMYTHE, OF EVANSTON, ILLINOIS, ASSIGNOR TO WESTERN ELECTRIC COMPANY, INCORPORATED, OF NEW YORK, N. Y., A CORPORATION OF NEW YORK.

CARRIER-WAVE COMMUNICATING AND SWITCHING SYSTEM.

Application filed March 12, 1924. Serial No. 698,609.

This invention relates to an improved interconnecting and communicating system, and more particularly to a system of the type in which carrier waves or oscillations, either free or guided, are employed as the medium for conveying energy for effecting the operation and control of the electrical switching, signaling and communicating apparatus located at separated points in the system. The invention especially relates to a system in which carrier currents in the form of high frequency waves guided upon wires are used as the medium of electrical connection between the electrical devices and apparatuses located at different points in the system. These carrier currents are assigned such frequencies that they are non-interfering with one another, so that each carrier serves as a connecting medium separate and distinct from the other carriers superposed upon the line or medium over which the carriers are transmitted. Each of the carriers is modulated in accordance with the voice currents or other signaling or controlling currents that are to be carried. The carriers thus modulated are transmitted over the toll or long distance line and are passed through individual arrangements each of which is selective of one carrier frequency to the exclusion of the others, and each of which may have associated with it apparatuses that serve to reproduce from a modulated carrier the voice, signal or controlling currents with which the carrier was modulated at the distant station. The arrangement which is used to transmit and receive by means of any one high frequency wave as distinguished from that which is used for transmitting and receiving by means of a wave of a different frequency is commonly known as a high frequency or carrier channel, or as a frequency selective channel.

The present invention is directed particularly toward providing a system in which a connection may be established between two or more toll or long distance stations through an intervening switching station or toll center and the carrier multiplex lines that connect the long distance stations with the toll center, preferably without the necessity of employing manually controlled switching or interconnecting agencies at the intermediate stations, although if desired, as illustrated in one of the modifications of the invention disclosed herein, the interconnecting operation at the switching station may be effected by an operator acting under instructions received from the distant or terminal toll stations; and toward providing a carrier multiplex interconnecting or switching system in which the switching or interconnecting of a channel of one line with a channel of a desired one of the other lines may be effected merely by the shifting of the carrier frequencies of the two channels at the intermediate station, and without the inclusion of any movable switch or relay contacts of any kind in the voice modulated carrier circuits. In the preferred embodiment of the invention herein disclosed, all of the transmitting and receiving branches of all of the channels of all of the carrier multiplex lines that center in the switching stations are permanently connected together in a plurality of groups by way of frequency selective paths that normally prevent any channel of any group from being in operative relation with any other channel of the same group; but which are able when the proper frequency shifting operations occur under the control of the operators at the distant toll stations, or if desired, under the control of an operator at the switching station, to afford operative connection in any combination desired between the various channels that center in each group, and therefore between the various lines which these channels represent.

The preferred embodiment of the invention is illustrated in the accompanying drawings, in which Fig. 1 is a schematic illustration of a carrier multiplex switching system organized in accordance with the principles of the present invention; Figs. 2 to 14, inclusive, taken together and arranged in the manner indicated in Fig. 16 show in as much detail as is necessary for understanding them the circuits of the complete organization that is illustrated schematically in Fig. 1. Figs. 2 and 3, 5 and 6, 8 and 9 and 11 and 12 illustrate the organization of the system at stations 1, 2, 3 and 4, respectively, of the system; Figs. 4, 7, 10 and 13 illustrate, respectively, the organization of the four switching or interconnecting groups at the switching station, and Fig. 14 shows the apparatus at the switching station for producing the demodulating and channel matching frequencies and for modulating

certain of the frequencies with a busy tone of station 2, channel 4 of station 3 and in connection with the production and transmission of a return busy test signal. Fig. 15 shows an alternative arrangement for preventing feed-back between the incoming channel branches of a switching group. Figs. 17 and 18 show a modified form of the invention. In this arrangement instead of the interconnection of the channels being controlled by the operators at the distant terminal toll stations, means are provided at the central switching station whereby they are interconnected by keys controlled by an operator thereat under instructions from a distant toll operator.

The circuit elements out of which the system illustrated in the drawings is built up are the same throughout the entire organization, and are all represented in any one of the four circuit groups comprised in Figs. 2, 3 and 4, Figs. 5, 6 and 7, Figs. 8, 9 and 10, or Figs. 11, 12 and 13. But the relationship between the circuit elements at each of the four stations of the system and in each of the four interconnecting groups at the switching station differ sufficiently from each other in each station group and in each switching group so that it has seemed desirable to show all of the groups in order that a clear understanding of the system organization may be obtained. These differences in circuit relationship resulting from the association of the elements in a complete switching system will be explained in the detailed description of the invention that is to follow.

The manner in which, in the present embodiment of the invention, the high frequency channels of the carrier multiplex toll lines are associated with each other at the switching station is illustrated in Fig. 1 of the drawing. As schematically illustrated there are four toll stations, station 1, station 2, station 3 and station 4, respectively, and a switching station in which the lines from the four toll stations center or converge. Each of the lines has superposed upon it four high frequency channels, which are designated in the drawing C-1, C-2, C-3 and C-4, respectively. At the switching station the sixteen channels of the four toll lines are associated for switching purposes in four groups designated group 1, group 2, group 3 and group 4, respectively. Each of the channels has two branches, one for transmitting in one direction and the other for transmitting in the opposite direction. The direction of transmission in these branches is indicated by the arrows associated with them. Each of the toll lines from the four outlying stations has a different channel associated with each of the four switching groups. Group 1 includes channel 1 of station 1, channel 2 of station 2, channel 3 of station 3 and channel 4 of station 4. Group 2 includes channel 2 of station 1, channel 3 of station 2, channel 4 of station 3 and channel 1 of station 4. Group 3 includes channel 3 of station 1, channel 4 of station 2, channel 1 of station 3 and channel 2 of station 4. Group 4 includes channel 4 of station 1, channel 1 of station 2, channel 2 of station 3 and channel 3 of station 4. Each of the four channels centering in each group is adapted to operate at a frequency different from the frequencies of the other three channels of the same group; and therefore, although all four lines represented by their respective channels in each group are physically connected with each other within the switching group, they are normally not operatively connected. The operative connection of one line with another within the group is effected by shifting the frequency of the receiving or incoming channel branch of one of the two lines that are to be interconnected to match the frequency at which the outgoing or transmitting branch of the other line is adapted to operate, and by shifting the frequency of the incoming channel branch of the other two lines to match the frequency at which the outgoing branch of the first mentioned line is adapted to operate. The manner in which this is accomplished will be explained in the detailed description that is to follow.

The frequency shifting or changing of the incoming channel branches that are to be interconnected in the switching group is effected under the control of certain lower controlling frequencies that are applied at the outlying or toll stations as a modulation of the carrier wave transmitted over each channel. Thus, as indicated in Fig. 1 of the drawing, the application of a modulating frequency of 75 cycles per second to any of the four channels terminating at station 1 causes a frequency shifting at the switching station that results in the channel of station 1 to which the modulation is applied being matched or connected with the channel of the corresponding group that is associated with station 2. The application of a modulating frequency of 150 cycles to any of the channels at station 1 causes the operative connection of the station 1 channel with the station 3 channel of the corresponding switching group; and the application of the 225 cycle modulating frequency to a channel at station 1 causes that channel to be operatively connected in its corresponding switching group with the channel of that group associated with station 4. Similarly at station 2 the application of 225 cycles to a channel causes it to be operatively connected with a channel extending to station 1; the application of the 75 cycle frequency results in interconnection with a channel extending to station 3; and the application of the 150 cycle frequency results in interconnection with a channel extending to station 4. At

station 3 the application of the 150 cycle modulation results in interconnection with station 1; the application of the 225 cycle modulation results in interconnection with station 2; and the application of the 75 cycle modulation results in interconnection with station 4. At station 4 the application of the 75 cycle modulation results in interconnection with station 1; the application of the 150 cycle modulation results in interconnection with station 2; and the application of the 225 cycle modulation results in interconnection with station 3. At each station the application of a particular one of the three modulating frequencies to any one of the channels terminating in that station causes that channel to be interconnected with a particular corresponding one of the other three stations, regardless of the channel to which the modulating frequency is applied and regardless of the particular one of the four switching station groups through which the interconnecting operation is effected.

The application of a particular modulating frequency to a channel not only causes the selective interconnection of that channel with a channel of the desired line in the switching station interconnecting group, but it also identifies at the called station the particular one of the other three stations which is calling. Thus the presence of the 225 cycle modulation upon the receiving branch of any of the channels at station 1 identifies the calling station as station 2; the presence of the 150 cycle modulation on a receiving channel branch at station 1 identifies the calling station as station 3; and the presence of the 75 cycle modulation identifies the calling station as station 4. At station 2 the presence of the 75 cycle, 225 cycle or 150 cycle modulation on the receiving branch of any of the four channels identifies the calling station as station 1, station 3 or station 4, respectively; at station 3 the presence of the 150 cycle, 75 cycle or 225 cycle modulation on the receiving branch of any of the channels identifies the calling station as station 1, station 2 or station 4, respectively; and at station 4 the presence of the 225 cycle, 150 cycle or 75 cycle modulation on the receiving branch of any of the channels identifies the calling station as station 1, station 2 or station 3, respectively.

In the particular embodiment of the invention that is illustrated schematically in Fig. 1, I have indicated generally the relationships that preferably exist when the system comprises four stations and carrier multiplex lines each with four frequency selective channels arranged for interconnection through the medium of four switching groups at the central or switching station. Of course, it will be understood that the principles of the invention are readily applicable to switching system arrangements wherein

the number of carrier multiplex lines, the number of frequency selective channels superposed upon each line and the number of interconnecting groups at the switching station differ from those in the organization 70 illustrated herein, which may be regarded merely as exemplary.

The general plan of organization of the system will now be described more in detail by reference to Figs. 2 to 13, inclusive, of 75 the drawing. The frequency selective channels associated with the carrier multiplex lines extending to stations 1, 2, 3 and 4 are shown, respectively, in Figs. 3, 6, 9 and 12 of the drawing, and the spring jack terminations of the channels at the four stations are shown in Figs. 2, 5, 8 and 11, respectively. The four interconnecting or switching groups at the switching station are shown in Figs. 4, 7, 10 and 13, respectively. The 80 springjack termination of the channels at the various stations is preferred on account of the simplification which it permits in circuit organization and system operation; but of course it will be understood that the channels 85 may be otherwise terminated in accordance with the well understood practices of the art in case it should be desired to do so. Referring particularly to Fig. 2 as illustrative of the scheme of channel termination that is 90 followed at all of the stations of the system, the springjack terminals are divided into an incoming group and an outgoing group, each of the groups being provided with as many 95 springjacks per channel as there are distant 100 stations with which interconnection may be had over that channel. Thus, as shown in Fig. 2, inasmuch as there are three distant stations with which each channel may be interconnected there are three springjacks in 105 each of the two main groups for each of the four channels terminating in station 1; that is there are four sets of three springjacks each in the incoming group and four sets of three springjacks each in the outgoing group. 110 Each springjack in each group has associated with it a signal or lamp, the lamps associated with the respective springjacks in the incoming group being calling signals, and the lamps associated with the springjacks in the main outgoing group being busy 115 signals. In the preferred form herein illustrated the twelve springjacks and lamps in each of the main groups are divided into four vertical rows corresponding with the 120 four switching groups with which the channels are associated at the switching station, and into three horizontal rows corresponding with the three distant toll stations with which interconnection may be had through 125 the medium of the four switching groups. At station 1, when station 2 is to be called, the toll plug TP of a pair of connecting cords, such as that illustrated at the left hand side of Fig. 2, is inserted into one or 130

- another of the four springjacks CJ—21, CJ—22, CJ—23 or CJ—24 in the first or upper horizontal row of springjacks in the outgoing group opposite which the character 5 S—2 appears. If it is station 3 that is to be called, the plug is inserted into one or another of the springjacks CJ—31, CJ—32, CJ—33 or CJ—34 in the second horizontal row opposite which the character S—3 appears. If station 4 is to be called the plug is inserted into one or another of the springjacks CJ—41, CJ—42, CJ—43 or CJ—44 in the third horizontal row opposite which the character S—4 appears. The particular 10 springjack that is chosen is one associated with a group the channel of which is not busy locally, the busy condition being indicated by the illumination of the busy lamps BL—1, BL—2, BL—3 or BL—4 of the four groups respectively.
- On the other hand, if the condition is one where a call is incoming to station 1 from station 2, one of the lamps CL—21, CL—22, CL—23 or CL—24 associated with the first 15 horizontal row in the main incoming group lights, depending upon the particular switching group and corresponding channel over which the call is coming. In like manner if the call is from station 3 one or another of the 20 calling lamps CL—31, CL—32, CL—33 or CL—34 in the second horizontal row of the incoming group lights; and if the call is from station 4 one or another of the calling lamps CL—41, CL—42, CL—43 or CL—44 25 in the third horizontal row lights, depending upon the switching group and corresponding channel over which the connection is being extended. Thus the calling lamp that lights indicates the station that is calling and the group and channel over which the call is coming, and the operator answers the call by inserting the toll plug TP of a pair of connecting cords, such as that designated CC, into the springjack associated 30 with the lighted lamp. The insertion of the plug TP into the particular springjack associated with the lighted calling lamp or into the particular springjack in the outgoing group associated with the station that is to be called and the switching group that is to be used, automatically brings about the energization of the proper channel and the application of the particular modulated control frequency to the energized channel for 35 creating the condition at the switching station and at the distant station necessary for the completion and control of the connection, as will be described in detail herein-after.
- 60 Each of the connecting cord circuits CC that is used for establishing connection with the channel terminals may be provided with a toll plug TP, a local plug LP, a ringing key RK, a listening key LK, a toll supervisory lamp TSL and a local supervisory
- another of the four springjacks CJ—21, lamp LSL with a supervisory relay for controlling it. One of the local lines, or trunks, with which the carrier multiplex channels may be connected through the medium of the connecting circuits such as CC is represented on the drawing by the local springjack LJ and the associated line lamp LL. Obviously any other of the well known arrangements available in the art for establishing connection between the different sorts 75 of circuits may be employed as desired.
- At the right-hand side of the characters S—2, S—3 and S—4, indicating the distant stations which the corresponding rows of springjacks in the incoming and outgoing 80 groups represent, are certain numbers in parentheses which indicate the modulating control frequencies that are automatically applied to the energized channel when a plug is inserted in a springjack of the corresponding 85 row in either the incoming or the outgoing group. Thus when a plug is inserted in the first row of springjacks in either group a 75 cycle modulating control frequency is applied; when the plug is inserted in a springjack in the second row in either group a control frequency of 150 cycles is applied; and when a plug is inserted in a springjack in the third row in either group, a control frequency of 225 cycles is applied. At the 90 left hand side of the characters S—2, S—3, and S—4 are other numbers in parentheses which indicate the modulating control frequencies the presence of which on the incoming branch of any of the channels identifies 95 the particular station from which the call is coming. Thus the presence of the 225, 150 or 75 cycle control frequency causes the lighting of the corresponding channel lamp in the first, second or third horizontal row, 100 respectively, and indicates that the call is from station 2, station 3 or station 4, as the case may be. Below the group designations 105 associated with the four vertical divisions of the incoming and outgoing groups of springjacks are the characters C—1, C—2, C—3 and C—4 which respectively indicate the 110 particular channel that represents the associated switching group at station 1.
- Referring briefly to Figs. 5, 8 and 11 indicating the channel terminal arrangement at stations 2, 3 and 4, respectively, the same system as that just referred to is used to indicate, by means of numbers or characters in parentheses, the modulating control frequencies automatically applied as a result 115 of inserting a plug into any of the springjacks of each corresponding horizontal row in the incoming and outgoing main divisions of springjack terminals, or the control frequencies that identify a call as being incoming from a particular distant station, and for indicating the particular channel that is 120 representative of each of the four switching groups at that particular station. In 125
- 65 130

view of the preceding description of the scheme of organization in connection with Fig. 1 of the drawing, which scheme of organization is that which is followed at the 5 four stations illustrated in Figs. 2, 5, 8 and 11 and is indicated by the frequency number and reference characters thereon, it is thought that no further description of the switching group, channel and modulating 10 control frequency relationships at the various stations of the system is necessary.

Referring now to the organization of the channels at the various stations as illustrated in Figs. 3, 6, 9 and 12 of the drawing, at 15 each station one of the four channels is shown completely in diagrammatic form, while the other three channels are indicated merely by rectangular spaces enclosed in broken lines. The channel that is shown 20 completely in diagrammatic form at each station is that channel which represents switching group 1 at that station, being channel 1 at station 1, channel 2 at station 2, channel 3 at station 3 and channel 4 at 25 station 4. At each of the four stations channel 1 is adapted to transmit upon the lower side band of the 23,333 cycle frequency and to receive on the upper side band of the 6,666 cycle frequency, channel 2 is adapted 30 to transmit on the lower side band of the 26,666 cycle frequency and to receive upon the upper side band of the 10,000 cycle frequency, channel 3 is adapted to transmit on the lower side band of the 30,000 cycle 35 frequency and to receive upon the upper side band of the 13,333 cycle frequency, and channel 4 is adapted to transmit on the lower side band of the 33,333 cycle frequency and to receive upon the upper side band of 40 the 16,666 cycle frequency.

The carrier multiplex line through which each terminal station has communication with the other stations of the carrier multiplex system is generally of the type disclosed 45 in Fig. 49 in the Colpitts and Blackwell paper entitled "Carrier current telephony and telegraphy" published in the Journal of the American Institute of Electrical Engineers for April, May and June, 50 1921. At each of the stations the associated carrier multiplex line is connected by way of a high frequency hybrid coil HFH, having a balancing network N, with a main transmitting branch and a main receiving branch 55 which connect with the transmitting and receiving branches of the various channels. At station 1 the connection with channel 1 is by way of band filters BF-1 and BF-2, with channel 2 by way of band filters BF-3 and BF-4, with channel 3 by way of band filters BF-5 and BF-6, and with channel 60 4 by way of band filters BF-7 and BF-8; and at the other stations there are similar connections. The toll line has connection 65 by way of the apparatus of channel 1, chan-

nel 2, channel 3 and channel 4 to the spring-jack terminals hereinbefore described, associated with the various channels. Associated with each channel there is a relay 50 which is responsive to the insertion of a plug 70 in any of the springjacks of the associated channel, and which controls the energization of the channel and the lighting of the busy lamps associated with the springjacks of the corresponding channel in the outgoing 75 group, and cooperates in the control of the calling lamps associated with the springjacks of the channel in the incoming group; relays 62, 63 and 64 that are responsive respectively to the application of the various control frequencies at the distant end of the channel and control the calling and supervisory lamps; relay 60 that operates whenever any of the relays 62, 63 and 64 is energized, and causes the lighting of the busy lamps of 80 the associated channel outgoing springjacks; and three relays 52, 53 and 54 that act under the control of the insertion of a plug in a springjack of one or another of the three 85 corresponding horizontal rows of springjacks to bring about the application of one or another of the three modulating control frequencies to the carrier of the associated 90 channel.

The band filters BF-1, BF-2, BF-3, 95 BF-4, BF-5, BF-6, BF-7 and BF-8, interposed in the various channel branches are so constructed and adjusted as to pass the frequency bands comprising in each case the appropriate side band of the modulated 100 carrier wave of the frequency indicated by the numerals associated with the rectangles representing these filters, the frequency bands for the various channels being in accordance with what has already been stated. 105 These and the other band filters designated as BF throughout the system are of the general type disclosed in Patent 1,227,113, issued May 22, 1917, to G. A. Campbell and also described, with respect to the specific 110 manner in which they are used in a carrier multiplex system of this type, in the Colpitts and Blackwell paper that has been referred to. As specifically illustrated in the case of channel 1 (Fig. 3), the frequency band that 115 passes through the band filter BF-2 included in the receiving branch is carried into the balanced detector BD-1 where it is joined by the corresponding carrier frequency selected from the common distributing circuit 115 by the band filter BF-20, the 6,666 cycle frequency in the case of channel 1. This frequency as well as all of the other frequencies required at the station 120 for modulation in the channel transmitting branches and for demodulating purposes in the channel receiving branches are produced and supplied to the distributing circuit 115 by means of harmonic generating apparatus 125 from a base frequency of 3,333 cycles sup- 130

plied to all of the stations from a common source so that the carriers at all of the stations of the system may be identical in their frequencies. The base frequency of 3,333 cycles, if desired, may be generated at the switching station and supplied over the various carrier multiplex lines to the outlying stations, at which it is received by way of a sub-branch, not shown, of the main receiving branch and utilized for the production of the required harmonic frequencies in the manner described in the Colpitts and Blackwell paper previously referred to, the nature and arrangement of the apparatus being in accordance with the disclosure contained in the patent to Burton W. Kendall, 1,446,752, dated February 27, 1923. As apparatus of this character is well known in the art, it has not been thought necessary to illustrate or particularly describe it.

As a result of the application of the received carrier side band and the corresponding 6,666 cycle frequency to the balanced detector BD-1, demodulation takes place in the balanced detector and the products of demodulation are modified in the amplifier A-1 and are thence carried to the low pass filter LPF-1 and the band filter BF-10. The low pass filter LPF-1 in the present instance is constructed and adjusted to have an upper cut-off limit of 300 cycles per second and the band filter BF-10 is constructed and adjusted to pass with substantially negligible attenuation a frequency band extending preferably from 300 to 2,300 cycles per second. The relatively low calling and controlling frequencies conveyed by the carrier pass through the low pass filter LPF-1, are distributed in accordance with their frequencies into the branches including tuned circuit TC-1, tuned circuit TC-2 and tuned circuit TC-3; and serve to energize the respectively associated relays 62, 63 and 64. In the particular arrangement shown the relays 62, 63 and 64 are relays that are adapted to attract their armatures and close the associated contact points as a result of the application of alternating currents to the relay windings. Relays of this type responsive to alternating currents of the frequencies employed for controlling purposes in the system as disclosed, are well known and available in the art; and consequently the relays 62, 63 and 64 are merely indicated by the usual conventional representation. If desired, the tuning of the three control frequency branches including tuned circuit TC-1 and relay 62, tuned circuit TC-2 and relay 63, and tuned circuit TC-3 and relay 64, respectively, may be accomplished by making the relay in each case an inductance element of the associated tuned branch, including such other inductance and capacity elements as may be necessary in each case to make each branch selective of the

particular control frequency to which the included relay is intended to respond. Or alternatively, if desired, each tuned branch may include a thermionic rectifier, in accordance with ordinary practice, for converting the alternating control frequency into unidirectional current, and the associated relay may then be an ordinary direct current relay.

The essential voice frequencies that pass from the output of amplifier A-1 through the band filter BF-10 are carried to the mid-points of the line windings of the low frequency hybrid coil LFH-1. One end of the line windings of the low frequency hybrid coil is connected through condensers with a low frequency balancing network N and the other end is connected through condensers and through an artificial line AL, which may be of the well known "H" type, by way of conductors 75 and 76 to the tip and ring or talking springs of each of the springjack branch terminals of the associated channel. The series winding of the low frequency hybrid LFH-1 is connected by way of the band filter BF-9 with the series input circuit of the balanced modulator BM-1 in the transmitting branch of the channel. The band filter BF-9 is of the Campbell type and is constructed and adjusted to pass a band of frequencies ranging from 300 to 2,300 cycles per second and to cut off frequencies above and below these limits. The input circuit of the balanced modulator BM-1 is also connected by way of the low pass filter LPF-2, adapted to pass frequencies up to 300 cycles per second, with the control frequency branches controlled in contacts of relays 52, 53 and 54, respectively. The control frequencies may be generated in harmonic producing apparatus of the sort illustrated and described in the Colpitts and Blackwell paper and in the Kendall patent hereinbefore referred to, as harmonics of a base frequency of 75 cycles per second. As apparatus of this sort is well known in the art, it is not thought necessary to illustrate or particularly describe it.

The organization of the balanced modulator BM-1 is in accordance with the disclosure of Patent 1,343,306 issued June 15, 1920, to J. R. Carson, the modulator being of what is commonly known as the balanced or carrier suppression type. That is, the effect of the potential variations in the divided input circuit of the modulator is balanced and neutralized in the output circuit excepting when the low frequency voice current fluctuations are impressed by way of the band filter BF-9 or when the low frequency calling or controlling current variations are impressed by way of the low pass filter LPF-2. Normally the carrier frequency supplied to the divided input circuit of the modulator from the distributing circuit 115 by way of the band filter BF-19 under the

control of relay 70 is balanced or neutralized in the output circuit; but when the voice frequencies or the controlling frequencies are applied to the series input circuit of the 5 modulator, the effects of the carrier current in the output circuit are no longer balanced, and consequently oscillations are produced in the output circuit having an amplitude proportionate to the instantaneous value of 10 the low frequency speech or low frequency controlling modulating currents.

The output side of the balanced modulator BM-1 is connected by way of a high pass filter HPF-1 with the input side of the 15 balanced amplifier BA-1. The high pass filter HPF-1 acts to prevent the passage of amplified and unmodulated low controlling and voice frequencies to the balanced amplifier BA-1 in order to prevent these frequencies from overloading the amplifier. 20 The balanced amplifier BA-1 is of the so called "push-pull" type, as illustrated and described in connection with Fig. 49 of the Colpitts and Blackwell paper hereinbefore referred to, and the high pass filter HPF-1 is of the sort also illustrated and described in the Colpitts and Blackwell paper. The output of the balanced amplifier BA-1 is connected by way of the band filter BF-1 25 with the main transmitting branch that joins the various channel transmitting branches with the high frequency hybrid coil HFH-1.

As the tubes of the balanced modulator 30 BM-1 and the balanced amplifier BA-1 are required to be active only when the associated channel is in use, the circuit of the A battery for heating the filaments of the tubes is controlled in contacts of the 35 relay 70 which are normally open and are closed only when the relay 70 is energized by the taking of the channel for use. The circuit of the A battery is illustrated as extending in parallel branches to the filaments 40 of the balanced modulator and to amplifier tubes; but it will be understood that this is merely a diagrammatic showing, and that the energizing circuits of the filaments of the 45 tubes may be connected with each other and the associated circuits in accordance with the standard practice of the wiring of these 50 devices. Inasmuch as it is desirable that the receiving branches of the various channels be normally in a responsive condition in order that they may constantly be in readiness to respond to a call originated at a 55 distant station, it is assumed that the thermionic tubes associated with the receiving branches have their filaments normally energized, and therefore the A battery circuit 60 for these tubes and means for controlling it are not shown.

The organization of the circuit and apparatus at the intermediate or switching station 65 will now be described by reference to

Figs. 4, 7, 10 and 13 of the drawing, which show the switching groups, group 1, group 2, group 3 and group 4, respectively. As has been explained hereinbefore each of these switching groups includes one channel 70 of each of the four carrier multiplex lines, line 1, line 2, line 3 and line 4 extending to station 1, station 2, station 3 and station 4, respectively. At the switching station a high frequency hybrid coil HFH-2 and a 75 balancing network N are connected with each of the carrier multiplex lines, in the usual way, and from the high frequency hybrid coil extend a main receiving branch and a main transmitting branch. The main 80 receiving branches of the four carrier multiplex lines are designated 116 and 117, 126 and 127, 136 and 137, and 146 and 147, respectively, and the main transmitting branches connected with the high frequency 85 hybrid coil of the various lines are designated 118 and 119, 128 and 129, 138 and 139, and 148 and 149, respectively. The main receiving branch and the main transmitting branch of each of the lines are connected with the appropriate sets of channel receiving branch and transmitting branch band filters of each of the four switching groups. The order in which the channels of the various lines are connected with the 90 four switching groups has been described in connection with the preceding explanation of the schematic diagram of Fig. 1; and in view of the complete showing in Figs. 95 4, 7, 10 and 13 of the interconnections of the 100 switching group channels with the four lines which each of these switching groups is adapted to serve, it is thought that no additional description of the relationship is necessary.

All of the channels of the various switching groups are similarly organized in all respects excepting those which have to do with the carrier frequencies that they are 105 designed to transmit and receive, the modulating frequencies that are applied to match the carriers of the receiving branches with the channel transmitting branches with which it is desired to have them co-operate 110 and the connection of the control frequency 115 responsive relays with the modulation frequency applying relays that they are required to control. The difference between the various channels with regard to these 120 controlling relationships will be explained 125 in connection with the detailed description of the operation of the system to follow. With respect to the basic features of organization of the various switching groups, a description of the organization of group 1 130 illustrated in Fig. 4 will suffice for all of them.

In switching group 1, channel 1 is connected by way of receiving branch band filter BF-11 and transmitting branch band 135

filter BF-12 with carrier multiplex line 1, channel 2 is connected by way of receiving branch filter BF-13 and transmitting branch filter BF-14 with line 2, channel 3 is connected by way of receiving branch filter BF-15 and transmitting branch filter BF-16 with line 3, and channel 4 is connected by way of receiving branch filter BF-17 and transmitting branch filter BF-18 with line 4. Each of the above mentioned band filters is adapted to pass the particular carrier side band of frequencies indicated by the numbers that are associated with the various filters. Referring now to the typical 15 channel circuit arrangement illustrated in connection with channel 1 of Fig. 4, the receiving branch extends from the band filter BF-11 to the series input circuit of the balanced modulator BM-2. The balanced modulator BM-2 is of the type disclosed in Patent 1,343,306 to Carson previously referred to, in which the currents to be modulated are applied serially to the input circuit of the two thermionic tubes of the 20 modulator and the modulating frequencies are applied by way of the common portion of the divided input circuit of the two tubes. In the case of channel 1 the currents that are communicated to the series input circuit of the balanced modulator BM-2 are the 25 currents comprised in the lower side band of the 23,333 cycle carrier that passes through the receiving branch band filter BF-11; and the modulating currents supplied to the 30 thermionic tubes of balanced modulator BM-2 in parallel are the harmonic modulating frequency of 23,333 cycles, corresponding to the carrier frequency of this particular receiving branch, and one or another of 35 the harmonic modulating frequencies of 33,333 cycles, 36,666 cycles or 40,000 cycles depending upon the particular called line channel the frequency of which is to be matched. The 23,333 demodulating 40 frequency and the particular desired one of the other three channel matching or carrier shifting frequencies are supplied to the parallel input circuit of the balanced modulator BM-2 through the medium of the 45 high frequency hybrid coil HFH-3. One end of the line windings of the high frequency hybrid coil is connected with the parallel input circuit of the balanced modulator and the other end of the line windings 50 is connected with the balancing net or impedance N, the value of which is so chosen as to balance the impedance of the input circuit of the balanced modulator. The midpoints of the high frequency hybrid coil HFH-3 are connected with the 23,333 cycle distributing circuit 101 (see Fig. 14), and the 55 series winding of the high frequency hybrid coil is connected with a circuit having branches extending to normally open front contacts of the relays 112, 113 and 114.

These three relays have their armatures connected respectively with the 33,333 cycle distributing circuit 104, the 36,666 cycle distributing circuit 105 and the 40,000 cycle distributing circuit 106 (see Fig. 14). The 60 back or resting contacts of each of the three relays 112, 113 and 114 are connected with the balancing impedances 16, 17 and 18, respectively, these impedances being of a magnitude to match the corresponding impedances introduced into the associated distributing circuits when the relays 112, 113 or 114 are operated to connect their corresponding distributing circuits with the 65 series windings of the high frequency hybrid coil HFH-3. This is in order that the impedance of each distributing circuit, looking out from the associated band filter of Fig. 14, may remain substantially constant regardless of the condition of use or disuse of 70 the various distributing circuit branches. The interposition of the high frequency hybrid coil HFH-3 in the circuit between the parallel input circuit of the balanced modulator BM-2 and the two harmonic 75 frequency modulating branches that are adapted simultaneously to feed modulating high frequency currents to the balanced modulator, maintains a conjugate relationship between the two branches so that while 80 each branch feeds its particular frequency into the input circuit of the balanced modulator neither branch impresses its frequency in any substantial amount upon the other 85 branch.

The modulating action which takes place in the balanced modulator BM-2 may now be briefly considered. The lower side band of the 23,333 cycle carrier that is applied to the series input circuit of the balanced modulator BM-2 is modulated by the 23,333 cycle harmonic frequency and also by one or another of the three harmonic frequencies 33,333, 36,666 or 40,000, depending upon which of the relays 112, 113 or 114 is actuated to close its front contacts. Considering first the modulation of the lower side band of the 23,333 cycle carrier by the 23,333 cycle harmonic frequency supplied through the hybrid coil HFH-3, the products of modulation which appear in the output circuit of the balanced modulator are primarily the amplified 23,333 cycle side band and the sum and difference products of modulation of this band with the 23,333 cycle harmonic frequency. The sum product of modulation is the lower side band of the 46,666 cycle frequency. The difference product of modulation is the relatively low frequency with which the 23,333 cycle carrier was modulated at the distant toll station to produce the side band that is passing through the band filter BF-11. In the 100 output circuit of the balanced modulator BM-2 are the band filter BF-21 and the 105

low pass filter LPF-3, filter BF-21 being constructed and adjusted to pass a band of frequencies ranging from 6,600 to 19,000 cycles and the filter LPF-3 being constructed and adjusted to pass a band of frequencies ranging from 0 to 250 cycles inclusive. Therefore, the particular controlling frequency of 75 cycles, 150 cycles or 225 cycles with which the carrier during the use of the channel is modulated at the distant toll station, is reproduced by demodulation in the balanced modulator BM-2 and flows from the modulator output circuit by way of the low pass filter LPF-3. All of the other products of modulation produced in the balanced modulator BM-2 by the modulation of the 23,333 cycle lower side band with the 23,333 cycle harmonic frequency are outside the range of both the filters BF-21 and LPF-3 connected with the modulator output circuit. The speech frequencies reproduced by this modulating action are limited to a range between 300 cycles and 2,300 cycles, and are therefore above the upper cut-off limit of low pass filter LPF-3 and are below the lower cut-off limit of band filter BF-21. Therefore, the only frequencies resulting from modulation by the 23,333 cycle frequencies that can pass from the output circuit of the modulator BM-2 are the 75 cycle, 150 cycle and 225 cycle controlling frequencies.

Substantially the same action as that described above occurs in each of the switching station receiving channel branches of all of the carrier multiplex lines when the corresponding channels are in use, as each channel has constantly applied to the parallel input circuit of its associated balanced modulator BM-2 the harmonic demodulating frequency corresponding to the carrier frequency of that channel. Therefore, in each case, the application of the 75 cycle, 150 cycle or 225 cycle controlling frequency at the toll terminal station of the channel results in the reproduction of that frequency in the output circuit of the associated balanced modulator BM-2 at the switching station, and the passage of the reproduced controlling frequency through the associated low pass filter LPF-3.

After passing through the low pass filter, the reproduced controlling frequency is amplified in amplifier A-2 and then flows through one or the other of the selective paths including the tuned circuits TC-4, TC-5, and TC-6, respectively, to the associated relays 12, 13 or 14. The relays 12, 13 and 14, like the relays 62, 63 and 64 of Fig. 3, although conventionally represented as ordinary relays, are relays constructed and adjusted to respond selectively to the alternating currents that reach them by way of their associated tuned circuits. Each of

the relays, if desired, may constitute one of the inductance elements of the associated tuned circuit, or if desired the alternating currents after passing through the tuned circuits TC-4, TC-5 and TC-6 may be rectified, and the resultant uni-directional current caused to actuate associated direct current relays in the usual way.

Returning now to a consideration of the action that occurs in balanced modulator BM-2 as a result of the modulation of the 23,333 cycle carrier lower side band by the harmonic frequencies applied under the control of relays 112, 113 and 114, it may be said in the first place that if the modulated carrier of channel 1 is to be matched with the frequency of channel 2, relay 112 is operated to apply the 33,333 harmonic frequency; if the modulated carrier of channel 1 is to be matched with channel 3, relay 113 is operated to apply the 36,666 cycle harmonic frequency; and if the modulated carrier of channel 1 is to be matched with channel 4, relay 114 is operated to apply the 40,000 cycle harmonic frequency. Assuming in the first place that the modulated 23,333 cycle lower side band of channel 1, associated with line 1 in group 1, is to be matched with channel 2 associated with line 2, it is necessary to change the lower side band of the 23,333 cycle carrier to the upper side band of the 10,000 cycle carrier, the latter being the side band that the outgoing or transmitting branch of channel 2 is adapted to pass by way of its band filter BF-14.

In this case as indicated above, the relay 112 is operated to apply the 33,333 cycle harmonic frequency to the parallel input circuit of the balanced modulator BM-2. The sum and difference products of modulation of the lower side band of the 23,333 cycle carrier with the 33,333 cycle harmonic frequency appear in the output circuit of the balanced modulator. The upper side band based upon the 10,000 cycle frequency appears as the difference product of modulation in the output circuit of the modulator, and this modulation product is within the frequency range of the band filter BF-21 connected with the modulator output circuit, and therefore passes through the filter. The sum product of modulation is the lower side band based upon a frequency of 56,666 cycles, which is outside the frequency range of the filter BF-21, and is therefore suppressed. All other products of modulation that appear in the output circuit of the modulator in any substantial amount are also outside the range of the filters connected with the output circuit and are therefore suppressed, so that the upper side band based upon the 10,000 cycle frequency is the only modulation product that is able to pass.

If it is assumed that the lower side band of the 23,333 cycle carrier of channel 1 is

to be matched with channel 3, in order to connect line 1 with line 3 in group 1, then relay 113 is operated to apply the 36,666 cycle harmonic frequency to the balanced modulator. The difference product of modulation of the 23,333 cycle lower side band and the 36,666 cycle harmonic frequency is the upper side band based upon the 13,333 cycle frequency. This corresponds with the frequency that the band filter BF-16 in the transmitting branch of channel 3 is constructed and adjusted to pass, and is also within the range of the band filter BF-21 connected with the output circuit of balanced modulator BM-2. Therefore, this modulation product with its speech or voice component passes through the band filter BF-21, while all of the other modulation products that appear in any substantial amount in the output circuit of the balanced modulator are outside the range of the filter BF-21 and are suppressed.

If the lower side band of the 23,333 cycle carrier of channel 1 is to be matched with channel 4, to establish connection between line 1 and line 4, relay 114 is operated to apply the 40,000 harmonic frequency to the balanced modulator BM-2. The difference product of modulation of the lower side band of the 23,333 cycle carrier and the 40,000 harmonic modulating frequency is the upper side band based upon the 16,666 cycle frequency. This is the frequency that the band filter BF-18 of the transmitting branch of channel 4 is adapted to pass, and is also within the frequency range of the band filter BF-21 connected with the output circuit of balanced modulator BM-2. All of the other modulation products that appear in the modulator output circuit in substantial amounts are outside of the frequency range of filter BF-21, and are therefore suppressed.

The same principle as that outlined in the foregoing applies in the case of the matching of the receiving branch carrier side bands of channel 2 with the transmitting branches of channels 1, 3 and 4 in the interconnection of line 2 with lines 1, 3 or 4, in the matching of the receiving branch carrier side band of channel 3 with the transmitting branches of channels 1, 2 and 4 in the interconnection of line 3 with lines 1, 2 or 4, and in the matching of the receiving branch carrier side band of channel 4 with the transmitting branches of channels 1, 2 and 3 in the interconnection of line 4 with lines 1, 2 or 3. That is, in each case the particular one of the three associated controlling relays of each channel is operated which applies that harmonic frequency, the difference modulation product of which with the receiving branch carrier side band is such as to result in the production of a side band corresponding with the frequency that

the band filter in the transmitting branch of the other channel is adapted to pass. Thus in the case of channel 2, the receiving branch carrier side band of which is the lower side band of the 26,666 cycle frequency, the matching of the 26,666 lower side band with channel 1 is accomplished by operating relay 121 to apply the 33,333 cycle harmonic frequency to the balanced modulator of channel 2 to produce the upper side band based on the 6,666 cycle frequency; the matching of channel 2 with channel 3 is accomplished by operating relay 123 to apply the 40,000 cycle harmonic frequency to produce the upper side band based upon the 13,333 cycle frequency; and the matching of channel 2 with channel 4 is accomplished by operating relay 124 to apply the 43,333 cycle harmonic frequency to produce the upper side band based on the 16,666 cycle frequency. In the case of channel 3, in which the lower side band of the 30,000 cycle carrier is employed in the receiving branch of the channel, the matching with channel 1 is effected by operating relay 131 to apply the 36,666 cycle harmonic frequency to the balanced modulator to produce in the output circuit the upper side band based upon the 6,666 cycle frequency, the matching of channel 3 with channel 2 is effected by operating relay 132 to apply the 40,000 harmonic frequency to produce the upper side band based upon the 10,000 cycle frequency, and the matching of channel 3 with channel 4 is effected by operating relay 134 to apply the 46,666 cycle harmonic frequency to produce in the output circuit of the modulator the upper side band based upon the 16,666 cycle frequency. In the case of channel 4, in which the lower side band of the 33,333 cycle carrier is employed in the receiving branch of the channel the matching of channel 4 with channel 1 is effected by operating relay 141 to apply the 40,000 cycle harmonic frequency to produce in the output circuit of the modulator the upper side band based upon the 6,666 cycle frequency, the matching of channel 4 with channel 2 is effected by operating relay 142 to apply the 43,333 cycle harmonic frequency to produce the upper side band based upon the 10,000 cycle frequency, and the matching of channel 4 with channel 3 is effected by operating relay 143 to apply the 46,666 cycle harmonic frequency to produce in the output circuit of the modulator the upper side band based upon the 13,333 cycle frequency.

As appears from the foregoing, each of the four channels of the group is provided with means for modulating the carrier side band incoming by way of its receiving branch in such a way as to shift its position in the frequency scale to match the frequency at which the transmitting or outgoing branch of any of the other three chan-

- nels of the group is adapted to operate. If the incoming carrier side band is to be directed into the transmitting branch of channel 1 it is changed to the upper side band based upon the 6,666 cycle frequency; if it is to be directed through the transmitting branch of channel 2 it is changed to the upper side band based upon the 10,000 cycle frequency; if it is to be directed through the transmitting branch of channel 3 it is changed to the upper side band based upon the 13,333 cycle frequency; and if it is to be directed through the transmitting branch of channel 4 it is changed to the upper side band based upon the 16,666 cycle frequency. In each case the frequency to which the received or incoming side band is converted is within the frequency range of the band filter, as BF-21, connected with the output circuit of the balanced modulator, which, as indicated, is constructed and adjusted to pass a band of frequencies extending from 6,600 cycles to 19,000 cycles per second. After passing through the band filter BF-21 the shifted carrier side band is amplified in balanced amplifier BA-2 and passes to a pair of conductors 150 which are common to all of the receiving and transmitting branches of the four channels of the group. That is, all of the incoming modulated carrier side bands of the various channels converge upon the common conductors 150; and from this common pair of conductors they are selectively distributed to the various channels by virtue of the frequency selective characteristics of the band filters included in the outgoing or transmitting branches of the four channels of the group.
- In order that there may be substantially no intermodulation between the plurality of frequencies that may be simultaneously applied to the common conductors 150 by the incoming branches of the various channels, the balanced amplifiers, as BA-2, interposed between the common conductors and each individual incoming channel branch, are so constructed and are made of such capacity as to have in effect a substantially linear characteristic throughout a considerable operating range. A repeater or amplifier of this type has the property of transmitting a plurality of frequencies separately and individually without providing their combination frequencies, as pointed out in the application of Burton W. Kendall, Serial No. 344,681, filed October 31, 1919, Patent No. 1,544,910, July 7, 1925; and the same properties that prevent the intermodulation of frequencies simultaneously applied to the input circuit of such a balanced amplifier or repeater are also effective to prevent intermodulation of a plurality of separate and individual frequencies that may, as in the present instance, be simultaneously present in the output or plate circuit as a result of their application to the common circuit to which the plate circuit is connected. Consequently, by the interposition of a balanced amplifier, as BA-2, between each individual receiving branch and the common conductors 150, the carrier side bands are kept individualized and cross talk which might otherwise occur is prevented.
- An alternative method for preventing intermodulation in the incoming or receiving branches of the frequencies that may simultaneously be applied to the common portion of the outgoing channel branches of the group, is illustrated in Fig. 15 of the drawing. In this alternative form, a conjugate relation of the incoming or receiving branches of the four channels of the group is established by the employment of the high frequency hybrid or conjugate coils HFH-5, HFH-6 and HFH-7. The incoming branches of two of the channels, as C-1 and C-2, are connected respectively with the series winding and the mid-points of the line windings of the high frequency hybrid coil HFH-5, and the incoming or receiving branches of the other two channels, as C-3 and C-4, are similarly connected with the series winding and the mid-points of the line windings of the high frequency hybrid coil HFH-6. One end of the line windings of each of the conjugate coils HFH-5 and HFH-6 is connected with an associated balancing impedance 87. The other end of the line winding of each of the two conjugate coils is connected with the high frequency hybrid coil HFH-7, one of the two coils HFH-5 and HFH-6 being connected with the series winding of the conjugate coil HFH-7 and the other being connected with the mid-points of the line windings of the conjugate coil HFH-7. One end of the line windings of the conjugate coil HFH-7 is connected with the balancing impedance 87 and the other end of the line windings is connected with the common pair of conductors 150 which have connection with the outgoing or transmitting branches of the channels C-1, C-2, C-3 and C-4, respectively. As a result of this arrangement the receiving branches of channels 1 and 2 are balanced with respect to each other in the high frequency hybrid coil HFH-5, the receiving branches of channels 3 and 4 are balanced with respect to each other in the high frequency hybrid coil HFH-6, and each pair is balanced against the other pair in the high frequency hybrid coil HFH-7. Consequently the incoming branches of all of the channels are free to feed toward the common outgoing branch conductors 150, but none of the incoming branches, on account of the balanced relation, is able to feed back into any other incoming branch. Where the alternative arrangement illustrated in Fig. 15 is employed

the balanced amplifiers BA-2 are not needed in the incoming or receiving channel branches as preventers of intermodulation between the various frequencies present in 5 the common circuit; but if desired they may remain in the organization merely as means for producing the desired gains in the transmitted side bands. In such case, however, they may better be replaced by a single repeating amplifier of the non-distorting type, 10 as indicated by the broken line rectangle in Fig. 15 and designated BA-1.

We may now consider briefly the apparatus illustrated in Fig. 14 for generating the 15 base frequency that is to be transmitted to the other stations of the system and the harmonic frequencies that are used at the switching station for effecting the frequency changes and modulations to which reference 20 has hereinbefore been made; also the apparatus for producing a busy tone modulation of certain of the carriers to be employed in case the channel associated with the line that is being called in any group is found to be 25 in use. The base frequency of 3,333, in the present instance, is generated in the oscillator O-1, which is preferably of any usual and well known thermionic type with a feed back connection from its output into its 30 input circuit. The sinusoidal oscillations produced in the oscillator O-1 are amplified in the amplifier A-4, have the magnitude of their voltages greatly increased in the transformer 19 and are then impressed upon 35 the input circuit of the harmonic generator HG-1. The magnitude of the impressed oscillations is such as greatly to overload the thermionic tube of the harmonic generator, with the result that the repeated oscillations are distorted into an extended 40 series of currents the frequencies of which are the harmonics of the base frequency currents. The above described action is in accordance with the disclosure contained 45 in the Kendall Patent 1,446,752 hereinbefore referred to.

The harmonics thus produced consist of 50 an extended series having relatively uniform energy values. After further amplification of these harmonic frequencies in amplifier A-5 the base frequency of 3,333 cycles is separated out by means of band filter BF-23 and is applied to the distributing circuit 100 from which it may be assumed to be supplied through the medium of appropriate band filters to the main transmitting branches of the different carrier multiplex lines centering in the switching station. The harmonic frequencies of 23,333 cycles, 55 26,666 cycles, 30,000 and 33,333 cycles are separated out by means of the band filters BF-24, BF-25, BF-26 and BF-27, respectively, and are then applied to the distributing circuits 101, 102, 103 and 104 from 60 which they are supplied to the balanced

modulators, as BM-2 of the various channels of the different carrier multiplex lines. As has been described, the 23,333 cycle frequency is supplied to the balanced modulators in the receiving branches of channels 70 1, the 26,666 cycle frequency is applied to the balanced modulators in the receiving branches of channels 2, the 30,000 cycle frequency is supplied to the balanced modulators in the receiving branches of channels 3, 75 and the 33,333 cycle frequency is supplied to the balanced modulators in the receiving branches of channels 4 of the various lines, these frequencies acting in each case to demodulate the received carrier band and reproduce the lower controlling frequencies with which the carrier may be modulated at the distant toll stations. The 36,666, 40,000, 43,000 and 46,666 cycle frequencies are separated out by means of band filters BF-28, 80 BF-29, BF-30 and BF-31 and are supplied by means of the distributing circuits 105, 106, 107 and 108 for the channel matching modulating operation under the control of the relays 112, 113 and 114, 121, 123 85 and 124, 131, 132 and 134 and 141, 142 and 143 of the various channels, as has been described; the 33,333 cycle frequency being also supplied by means of its distributing circuit 104 for channel matching modulation 90 purposes as well as for the demodulation of the carrier side band of channel 4.

The production of the busy tone modulation is effected in the balanced modulator BM-4 (Fig. 14) by the modulation of the 100 6,666, 10,000, 13,333 and 16,666 cycle frequencies by a busy tone current supplied from any suitable source. The busy tone is preferably one which contains no frequency components of the order of the 105 75 cycle, 150 cycle and 225 cycle frequencies employed in the system for controlling the switching and supervisory apparatus; or, if such components are present they may be suppressed by supplying the busy tone 110 through a band filter constructed and adjusted to suppress these lower frequencies and the frequencies above the ordinary voice frequency range. The busy tone modulation of the four carriers referred to is amplified in amplifier A-6 and is applied by 115 way of band filter BF-33 having a frequency range of from 6,600 to 19,000 cycles to the distributing circuit comprising the conductors 151 and 152, from which circuit it is supplied when needed to the outgoing or transmitting branch of each channel under the control of the relays 10, 20, 30 and 40. The busy tone is supplied as a modulation of the four carriers of 6,666, 10,000, 120 13,333 and 16,666 cycle frequencies so that it may be furnished over a single distributing circuit to all of the outgoing channel branches and may be capable of passing 125 through the transmitting branch filter of any 130

channel to which it may be applied. The energization of the balanced modulator BM-4 and the amplifier A-6 of the busy tone modulating apparatus is under the control 5 of the relay 25, which is energized over conductor 153 whenever any of the relays 10, 20, 30 or 40 is actuated, to connect the A battery for the lighting of the filaments of the balanced modulator and amplifier tubes.

10 To simplify and economize space in the drawing the connection of the distributing circuits 100 to 108, inclusive, of Fig. 14 with the various channel branches for applying the harmonic frequencies to the balanced 15 modulators are not shown, but the connections in each case are indicated by the numbers and reference characters placed opposite the terminations of the various channel demodulating branches shown in Figs. 4, 7, 20 10 and 13. Opposite each of the relay controlled branches leading through the high frequency hybrid coil to the balanced modulator in each channel receiving branch there are three designations. The third of 25 these indicates the harmonic frequency applied by way of the pair of conductors; the first indicates the channel with which the associated channel is brought into operative relation by the application of this frequency; and the second, in parentheses, indicates the station to which the station of 30 the associated channel becomes connected through the application of the indicated modulating frequency. Thus, for instance, 35 in the case of channel 1 shown in Fig. 4, this channel represents station 1, as indicated by the legend that appears at the left of the connection of the channel branches with the main distributing branches; and, as explained, 40 the notations which appear in connection with the conductors extending to the left from the armatures of relay 112 indicate that the application of the 33,333 cycle modulating frequency to the balanced 45 modulator of channel 1 causes this channel to become operatively associated with channel 2, and with station 2 with which channel 2 is identified in the group shown in Fig. 4.

50 With respect to the channel interconnections that result from the application of a particular modulating frequency to a particular channel, the four switching groups illustrated in Figs. 4, 7, 10 and 13 are all 55 alike, in each case the application of a particular modulating frequency to a particular channel bringing about the interconnection of that channel with a particular other channel in a corresponding manner throughout 60 the groups. But as each group differs from each other group with respect to the particular station which the corresponding channel represents throughout the groups, corresponding channel interconnections in the various 65 groups result in different station inter-

connections. This relationship is more readily apparent from an inspection of the four groups illustrated in Figs. 4, 7, 10 and 13 and the notations associated with the various channels of each group than it would be by 70 an attempted detailed description, which therefore will be omitted.

We may now consider the manner in which the groups are organized with respect to the control exercised by the relays 12, 13 and 14, 21, 23 and 24, 31, 32 and 34, and 41, 42 and 43 over the modulating frequency applying relays 112, 113 and 114, 121, 123 and 124, 131, 132 and 134, and 141, 142 and 143. Inasmuch as all of the groups are alike in the 80 matter of the channel interconnections one with another a description of the relay control relations of group 1 (Fig. 4) will suffice for all.

Associated with each of the channels are 85 three controlling relays, one for each possible interconnection of that channel with the remaining three channels of the group. In the case of channel 1, relay 12 is operated to connect channel 1 with channel 2, relay 13 is 90 operated to connect channel 1 with channel 3 and relay 14 is operated to connect channel 1 with channel 4. In the case of channel 2, relay 21 is operated to connect channel 2 with channel 1, relay 23 is operated to connect channel 2 with channel 3, and relay 24 is operated to connect channel 2 with channel 4. In the case of channel 3, relay 31 is operated to connect channel 3 with channel 1, relay 32 is operated to connect channel 3 with channel 2, and relay 34 is operated to 95 connect channel 3 with channel 4. In the case of channel 4, relay 41 is operated to connect channel 4 with channel 1, relay 42 is operated to connect channel 4 with channel 2, and relay 43 is operated to connect channel 4 with channel 3. The channel interconnections which result from the operation of these relays are indicated by the notations 100 at the right of each relay, and the notations 105 which appear in parentheses at the right of each relay indicate the station interconnections which result from the operation of the associated relay. This is true with respect to the corresponding relays of the other 110 three groups illustrated in Figs. 7, 10 and 13. The three controlling relays of each channel are controlled selectively from the station to which the channel extends in accordance with the particular control frequency of 75 cycles, 150 cycles or 225 cycles that may be applied as carrier modulation at the distant station. When any one of the twelve controlling relays of the four channels of the group is operated it energizes one or another of the six conductors 81, 82, 83, 84, 85 and 86. In operating relay 12 or relay 21 energizes conductor 81, relay 34 or relay 43 energizes conductor 82, relay 13 or relay 31 energizes conductor 83, relay 24 115 120 125 130

or relay 42 energizes conductor 84, relay 14 or relay 41 energizes conductor 85, and relay 23 or relay 32 energizes conductor 86. It will be observed that in each case a pair of relays, the operation of which serves to energize any particular conductor, is the pair of relays either one of which is operated to bring about the interconnection of the same two channels. Thus relay 12 of channel 1 is adapted to connect channel 1 with channel 2, and relay 21 of channel 2, which also is arranged to energize conductor 81, also is adapted to complete the interconnections of channels 1 and 2 by connecting channel 2 with channel 1.

The operation of the channel interconnecting relays 112, 113, 114, 121, 123, 124, 131, 132, 134, 141, 142 and 143 by the control relays 12, 13, 14, 21, 23, 24, 31, 32, 34, 41, 42 and 43 is subject to the control of the relays 1-2, 3-4, 1-3, 2-4, 1-4 and 2-3 of a blocking group associated with each of the four switching groups. The hyphenated numerals used to designate the various relays of this group indicate the two channels which each relay is adapted to effect the interconnection of in its operation. The channel interconnection effected by each relay is also indicated by the notations located below each relay of the group, and the associated notations enclosed in parentheses indicate the station interconnection which each relay of the blocking group is adapted to bring about when it is operated. Each of the conductors 81, 82, 83, 84, 85 and 86 associated with the control relays 12, 13, 14, etc., extends to the energizing winding of one of the relays of the blocking group through normally closed contacts of other relays of the group. Thus, conductors 81 and 82 extend respectively to the energizing windings of relays 1-2 and 3-4 by way of back contacts of the relays 1-3, 2-4, 1-4, and 2-3; conductors 83 and 84 extend to the energizing windings of relays 1-2 and 3-4, respectively, through back contacts of the relays 1-2, 3-4, 1-4 and 2-3; and conductors 85 and 86 extend to the energizing windings of relays 1-4 and 2-3, respectively, by way of back contacts of the relays 1-2, 3-4, 1-3 and 2-4. As a result of this circuit relationship each relay in operating to bring about the interconnection of the associated two channels opens and renders non-effective the energizing circuits of all of the relays of the blocking group which might otherwise be operated to bring either one of the two interconnected channels into operative relation with any other channel, but does not open, and leaves effective the energizing circuit of the complementary relay which is operated to effect the interconnection with each other of the remaining two channels of the four in the group. Thus,

for instance, when the relay 1-2 is operated to effect the interconnection of channels 1 and 2, it opens the energizing circuit of relay 1-3 adapted to connect channel 1 with channel 3, the circuit of relay 2-4 adapted to connect channel 2 with channel 4, the circuit of relay 1-4 adapted to connect channel 1 with channel 4, and relay 2-3 adapted to connect channel 2 with channel 3. But it does not open the energizing circuit of relay 3-4, which consequently is free to operate to bring about the interconnection of the remaining two channels of the group, channels 3 and 4, in case the station associated with either of the channels initiates a call for the station associated with the other channel. In like manner when either of the relays 1-3 or 2-4 is energized to effect the interconnection of the channels indicated by the hyphenated numbers, it leaves the other of the two relays free to operate, but blocks the remaining four relays by opening their energizing circuits; and when either of the two relays 1-4 and 2-3 operates it leaves the associated relay of the pair free to effect the interconnection of its associated channels, but opens the energizing circuits of and blocks the remaining four relays of the group.

Each of the six relays 1-2, 3-4, 1-3, 2-4, 1-4 and 2-3 in operating causes the energization of the corresponding one of the conductors 91, 92, 93, 94, 95 and 96; and each of these conductors when it becomes energized brings about the operation of the appropriate pairs of relays for causing the application to the balanced modulator of each channel of the harmonic modulating frequency necessary to match the carrier side band of the receiving branch of the channel with the transmitting or outgoing branch of the channel with which the connection is to be completed. Thus when relay 1-2 is energized as a result of the operation of relay 12 of channel 1 or relay 21 of channel 2 it energizes conductor 91 and brings about the operation of relay 112 of channel 1 and relay 121 of channel 2. Relay 112 of channel 1 applies the 33,333 cycle frequency to the balanced modulator in the receiving branch of that channel and changes the received lower side band of the 23,333 cycle carrier to the upper side band of the 10,000 cycle carrier, which is adapted to pass through the band filter BF-14 in the transmitting branch of channel 2. Relay 121 of channel 2 in operating applies the 33,333 cycle frequency to the balanced modulator in the receiving branch of channel 2, and changes the received lower side band of the 26,666 cycle carrier to the upper side band of the 6,666 cycle carrier, which is adapted to pass out through the band filter BF-12 in the transmitting branch of chan-

nel 1. Therefore, the operation of relay 1-2 in the blocking group puts channel 1 and channel 2 in operative relation with each other. Each of the other five relays in the blocking group operates in a similar manner to energize the appropriate pair of relays associated with the two channels that are to be interconnected, and thus to apply the proper modulating frequencies to the balanced modulators in the receiving branches of the two channels to match the received carrier side band of each with the frequency at which the transmitting or outgoing branch of the other is adapted to operate. Each of the groups of interconnecting relays as 112, 113 and 114 has associated with it a common relay, as 110, that is actuated when any one of the three relays of the associated group is operated, to connect A battery with the filaments of the balanced amplifier, as BA-2, of the receiving branch of the associated channel; and associated with each group of control relays, as 12, 13 and 14, is a relay, as 10, that is energized in a manner that will hereinafter be described, when the intended connection is blocked in the group of blocking relays to energize the busy tone producing apparatus and apply a busy tone modulation to the channel extending back to the calling station.

The manner in which the system of the present invention operates to effect interconnection between a calling station and a called station will now be described. We may assume, for the purpose of illustration, that station 1, shown in Fig. 2, is the calling station, that station 4, shown in Fig. 11, is the called station, and that the connection between the two stations is completed by way of switching group 1 shown in Fig. 4. When the operator at station 1 has made connection with the local calling subscriber's line by means of the local plug of a pair of connecting cords CC and has learned that the toll station with which connection is desired is station 4, she picks up the toll plug TP of the pair of cords and inserts it in any one of the springjacks CJ-41, CJ-42, CJ-43 or CJ-44 representing Station 4 in the outgoing group of springjacks, the busy lamp BL-1, BL-2, BL-3 or BL-4 of which is not illuminated. If any of the channels corresponding to the four pairs of calling springjacks and busy lamps is in use in consequence of either an outgoing or incoming call, the associated busy lamp is illuminated, the channels that may be available for the establishment of the connection thus being indicated to the operator by the unilluminated condition of the associated busy lamps. Assuming that the busy lamp BL-1 associated with calling springjack CJ-41 corresponding to called station 4 is not lighted, the operator at station 1 inserts the toll plug TP into

this springjack. This completes a circuit that extends from battery through toll supervisory lamp TSL of the connecting cord circuit, registering sleeve contacts of the toll plug TP and springjack CJ-41, conductor 77 and winding of relay 50 to ground. As a result the toll supervisory lamp TSL is illuminated and the relay 50 is operated. Relay 50 in moving its three left hand armatures from their back to their front contacts deprives the channel supervisory relays 62, 63 and 64 of the control that they normally have by way of conductors 66, 67 and 68 over the corresponding calling lamps CL-21, CL-31 and CL-41 associated with springjacks AJ-21, AJ-31 and AJ-41 of the incoming group, and gives whichever one of them is subsequently actuated control over the toll supervisory lamp TSL of the connecting cord circuit. Relay 50 in operating also applies current by way of its outer right hand armature and front contact and conductor 65, for lighting the busy lamps BL-1 of the group of springjacks in the outgoing group, and also applies current by way of its inner right hand armature and front contact for the operation of relay 70. Relay 70 in operating connects the A battery with the balanced modulator BM-1 and balanced amplifier BA-1 for

the energization of the transmitting branch of channel 1, and applies the 23,333 cycle frequency to balanced modulator BM-1 in readiness to be modulated by the low frequency voice and controlling currents that may be applied to the series input circuit of balanced modulator BM-1. The insertion of toll plug TP into calling springjack CJ-41 representing station 4 in the outgoing group also closes a circuit that extends from battery through the winding of relay 54 (Fig. 3), conductor 74, and the local switch spring and contact of springjack CJ-41 to ground. This results in the application of the 225 cycle control frequency by way of low pass filter LPF-2 to the series input circuit of balanced modulator BM-1. Consequently the 23,333 cycle carrier modulated with the 225 cycle control frequency passes from the output circuit of balanced modulator BM-1 through the high pass filter HPF-1 to the input circuit of balanced amplifier BA-1, and the lower side band of this carrier modulation, after amplification in balanced amplifier BA-1, passes by way of band filter BF-1 and the high frequency hybrid coil HFH-1 to the conductors of line 1 extending to the switching station.

At the switching station the lower side band of the 23,333 cycle carrier passes through band filter BF-11 in the receiving branch of channel 1 of group 1 to the series input circuit of balanced modulator BM-2. Here it is met by the 23,333 cycle

demodulating frequency applied to the parallel input circuit of balanced modulator BM-2 by way of the high frequency hybrid coil HFH-3, and the 225 cycle control frequency applied at the calling station appears in the output circuit of the balanced modulator BM-2. This frequency is within the frequency range of low pass filter LPF-3 connected with the output circuit, and consequently passes through low pass filter LPF-3, is amplified in amplifier A-2, and passes selectively through tuned circuit TC-6 to relay 14, which relay is thereupon energized and caused to attract its armature.

Assuming that none of the relays 1-2, 3-4, 1-3 or 2-4 is in operative condition at this time, the energization of relay 14 closes a circuit that extends from battery through the winding of relay 10, armature and front contact of relay 14, conductor 85, resting contacts of relays 2-4, 1-3, 3-4 and 1-2 in series, and the winding of relay 1-4 to ground. Relay 1-4 thereupon operates, opens at its four upper armatures and resting contacts the energizing paths by way of conductors 81, 82, 83 and 84 to the associated relays of the blocking group, and at its lower armature and front contact closes a circuit that extends from battery in parallel paths through the windings of relay 114 of channel 1 and relay 141 of channel 4, conductor 95, and the lower front contact and armature of relay 1-4 to ground. The winding of relay 110 is included in the path from battery to the winding of relay 114, and the winding of relay 140 is included in the path from battery to the winding of relay 141. Therefore, as a result of the operation of relay 1-4 of the blocking group, relays 110 and 114 of channel 1 and relays 140 and 141 of channel 4 are operated. Relay 110 of channel 1 in operating applies current from the A battery for the heating of the filaments of balanced amplifier BA-2 in the receiving branch of channel 1, and relay 140 of channel 4 in operating applies current from the A battery for the heating of the filaments of balanced amplifier BA-3 in the receiving branch of channel 4. The balanced amplifiers BA-2 and BA-3 of channels 1 and 4 thus become energized in readiness to transmit the modulated carrier side bands for interconnection and intercommunication between calling station 1 and called station 4 of switching group 1.

The operation of relay 141 of channel 4 applies 40,000 cycle modulating frequency to the parallel input circuit of balanced modulator BM-3 by way of the high frequency hybrid coil HFH-4; and as the 33,333 cycle modulating frequency is being constantly applied to the balanced modulator BM-3, these two frequencies are now present in the input circuit of the balanced modulator.

But inasmuch as they are applied in balanced relation with respect to the two tubes and their common output circuit, they do not produce any flow of current in the circuit extending from the balanced modulator BM-3 to the associated band filter BF-22 and low pass filter LPF-4. They do not become effective until the lower side band of the 33,333 cycle carrier is applied to the series input circuit of balanced modulator BM-3 by way of the band filter BF-17, which does not occur until channel 4 is energized at the called station.

Relay 114 of channel 1 in operating applies the 40,000 cycle modulating frequency by way of the high frequency hybrid coil HFH-3 to the parallel input circuit of the balanced modulator BM-2. Among the modulation products of the 40,000 cycle frequency with the lower side band of the 23,333 cycle carrier applied to the balanced modulator series input circuit by way of band filter BF-11 is the difference modulation product of the 40,000 cycle frequency and the 23,333 cycle carrier lower side band which is the upper side band of the 16,666 cycle frequency. This side band is within the frequency range of band filter BF-21. It consequently passes through the band filter, is amplified in balanced amplifier BA-2 and is communicated to the common conductors 150 from which the four outgoing channel branches diverge. The only branch that selectively permits the passage of the 16,666 cycle upper side band is the branch by way of band filter BF-18 of channel 4. Therefore the 16,666 cycle carrier, with the 225 cycle control frequency modulation applied at calling station 1, passes through band filter BF-18 of channel 4, conductors 148 and 149, high frequency hybrid coil HFH-8 (Fig. 13), line 4, high frequency hybrid coil HFH-9 at station 4 (Fig. 12), band filter BF-35 of channel 4 at station 4, to the series input circuit of balanced detector BD-2 in the receiving branch of channel 4. The 16,666 cycle frequency applied by way of band filter BF-35 to the parallel input circuit of balanced detector BD-2 causes the demodulation of the 16,666 cycle carrier side band and the demodulation products are amplified in amplifier A-7. The 225 cycle control frequency reproduced as a result of the demodulation in balanced detector BD-2 passes through low pass filter LPF-5 and is selectively directed by way of tuned circuit TC-10 to the winding of relay 161, which relay is thereupon energized.

Relay 161 in operating closes a circuit that extends from battery through the winding of relay 160, the armature and front contact of relay 161, inner left hand armature and back contact of relay 51, conductor 166, and lamp CL-11 (Fig. 11) to ground, thus

lighting the lamp and energizing relay 160. As may be observed from the notations on Fig. 11 representing station 4, the position of lamp CL-11 and associated answering jack AJ-11 indicates to the operator that a call is incoming from station 1 by way of group 1, and the operator answers the call by inserting the toll plug TP of one of her pairs of connecting cords CC into the spring-jack AJ-11 associated with the lighted calling lamp.

The insertion of the station 4 operator's toll plug into the answering jack associated with the lighted calling lamp automatically sets up the circuit conditions necessary to extend the circuit of the connecting cords that she uses over the proper channel and by way of the proper group at the switching station to the particular channel of the particular calling station that has initiated the call. Nothing in the way of a selective operation on the part of the called station operator is required other than merely to make connection with the answering spring-jack associated with the calling lamp that lights.

When the toll plug TP at station 4 is inserted in spring-jack AJ-11, a circuit is completed that extends from battery through toll supervisory lamp TSL, registering sleeve contacts of toll plug TP and spring-jack AJ-11, conductor 177 and winding relay 51 (Fig. 12) to ground. Relay 51 in operating opens the back contacts and closes the front contacts of its left hand armatures. The opening of the back contact of the inner left hand armature breaks the circuit by way of the conductor 166 over which the calling lamp CL-11 was lighted, and extinguishes the lamp. A branch circuit from battery is at the same time completed that extends by way of the winding of relay 160, armature and front contact of relay 161, inner left hand armature and front contact of relay 51 to ground by way of the winding of relay 51, which shunts out and extinguishes the toll supervisory lamp TSL of the operator's connecting cord circuit CC. The resistance of the winding of relay 160 is so proportioned to the resistance of toll supervisory lamp TSL and to the resistance of the winding of relay 51 as to produce this result. When relay 160 was first operated as a result of the closure of the energizing circuit of calling lamp CL-11 in the contacts of relay 161, it closed a circuit extending from battery by way of the armature and front contact of relay 160, conductor 165, and busy lamps BL-1 associated with the calling spring-jacks of group 1 at station 4, thus immediately indicating to the operator at station 4 the busy condition of the associated group. When relay 51 operates in response to the insertion of toll plug TP into answering spring-jack AJ-11, as described, battery is also applied to con-

ductor 165 by way of the outer right hand armature and front contact of relay 51 so that the busy lamps BL-1 are kept lighted to indicate the busy condition of the associated channel as long as either relay 51 or 70 relay 160 is energized. Relay 51 in operating also closes a circuit at its inner right hand armature and front contact that extends from battery through the winding of relay 180 to ground; and relay 180 in operating applies current from the A battery for the heating of the filaments of the tubes of balanced modulator BM-5 and balanced amplifier BA-5 and also applies the 33,333 cycle frequency by way of band filter BF-80 38 to the parallel input circuit of balanced modulator BM-5 in readiness for modulation by the low frequency voice and control currents that will be applied to the transmitting branch of the channel. 85

The insertion of the toll plug TP into answering spring-jack AJ-11 in answering the incoming call also closes a circuit that extends from battery through the winding of relay 181 (Fig. 12), conductor 171, and local contacts of spring-jack AJ-11 to ground. Relay 181 is thereupon energized to apply the 75 cycle control frequency to the series input circuit of balanced modulator BM-5 by way of low pass filter LPF-95 6. The 33,333 cycle carrier thus modulated with the 75 cycle control frequency passes through high pass filter HPF-2, is amplified in balanced amplifier BA-5, and the lower side band of the 33,333 cycle carrier 100 passes by way of band filter BF-34 and high frequency hybrid coil HFH-9 to line 4 extending to the switching station. At the switching station the 33,333 cycle lower side band passes by way of high frequency hybrid coil HFH-8, the common incoming conductors 146, 147 and band filter BF-17 of channel 4, group 1 (Fig. 4), to the series input circuit of balanced modulator BM-3.

Here modulation by the 33,333 cycle frequency and the 40,000 cycle frequency, the latter applied by way of the contacts of relay 141, occurs. The modulation of the carrier side band by the 33,333 cycle frequency reproduces the 75 cycle control frequency applied at the called station, station 4, and this control frequency passes by way of low pass filter LPF-4 and amplifier A-3 and is directed to the winding of relay 41 by way of the tuned circuit TC-7. Relay 41 in operating closes a circuit that extends from battery through the winding of busy tone controlling relay 40 of channel 4, armature and front contact of relay 41, conductor 85, normally closed contacts of relays 2-4, 1-3, 3-4 and 1-2 of the blocking group and winding of relay 1-4 to ground. Consequently relay 1-4 of the blocking group is now energized by the current applied to conductor 85 over two branch paths, one closed 125 130

by relay 14 of channel 1, and the other closed by relay 41 of channel 4. Neither of the busy tone controlling relays 10 and 40 is energized, as these relays are so constructed and adjusted that the current which flows through them when the winding of one of the blocking relays is in series in the circuit is insufficient to cause their actuation. Inasmuch as relay 1-4 of the blocking group 5 is already in an operated condition as a result of the operation of relay 14 of channel 1, and is acting, as has been described, to hold energized the modulation frequency controlling relays 114 of channel 1 and 141 of channel 4, no change in the operative condition at the switching station results at this time from the energization of relay 41 of channel 4.

The modulation of the incoming lower side band of the 33,333 cycle carrier from station 4 in balanced modulator BM-3 of channel 4 by the 40,000 cycle frequency applied by way of the contacts of relay 141, results in the production in the output circuit 10 of balanced modulator BM-3 of the upper side band of the 6,666 cycle carrier. This passes through the band filter BF-22 and balanced amplifier BA-3, to the common conductors 150. The only one of the outgoing branches from the conductors 150 that is tuned to permit the passage of the 6,666 cycle carrier upper side band is the outgoing or transmitting branch of channel 1. Consequently this side band, carrying the 15 75 cycle control frequency modulation of called station 4, passes by way of band filter BF-12, outgoing conductors of 118, 119, and high frequency hybrid coil HFH-2 to line 1 extending to station 1. At station 1 the 6,666 cycle carrier upper side band passes by way of high frequency hybrid coil HFH-1 and band filter BF-2 to balanced detector BD-1 of channel 1. Here it is met by the 6,666 cycle frequency applied by way 20 of band filter BF-20, and the products of demodulation thence flow through amplifier A-1 to the branched circuits extending to low pass filter LPF-1 and band filter BF-10. The 75 cycle control frequency which is 25 reproduced by the demodulating action in balanced detector BD-1 passes through low pass filter LPF-1 and is diverted through tuned circuit TC-3 to the winding of relay 64, which relay thereupon attracts its armature. This closes a circuit that extends from battery by way of the winding of relay 60, armature and front contact of relay 64, outer left hand armature and front contact of relay 50, this relay having been 30 energized by the insertion of the plug in the corresponding springjack in the initiation of the call, and winding of relay 50 to ground. This path from battery completed by the operation of relay 64 is in shunt of the path to battery through the winding of

relay 50 completed by way of the toll supervisory lamp TSL and conductor 77 upon the insertion of the toll plug TP into calling springjack CJ-41, with the result that the operation of relay 64 shunts out 70 and extinguishes the toll supervisory lamp associated with the pair of connecting cords used by the station 1 operator in initiating the call.

Consequently the response of the operator at called station 4 is indicated to the operator at station 1 by the extinguishing of the toll supervisory lamp TSL.

Calling station 1 and called station 4 are now in communication through the medium 80 of channel 1 of the station 1 line channel 4 of the station 4 line and switching group 1 at the intermediate or switching station, and the operators at the two stations may converse. The voice currents from station 1 85 (Fig. 2) pass from the operator's telephone apparatus associated with the connecting cord circuit by way of the registering tip and ring contacts of toll plug TP and calling springjack CJ-41, conductors 75 and 90 76, artificial line AL, low frequency hybrid coil LFH-1, band filter BF-9, to the transmitting branch of channel 1 of station 1 in which they, together with the low control frequency of 225 cycles, modulate the 95 23,333 cycle carrier and are applied in the form of a modulated carrier wave to line 1 by way of band filter BF-1 and high frequency hybrid coil HFH-1. At the switching station, the modulated carrier 100 wave produced at station 1 passes through the receiving branch of channel 1 of group 1 and after appropriate modulation, as has been described, passes out by way of the transmitting branch of channel 4 and the 105 high frequency hybrid coil HFH-8 (Fig. 13) to line 4 extending to station 4. At station 4 the modulated carrier passes by way of band filter BF-35 (Fig. 12) to the receiving branch of channel 4, and after 110 demodulation the voice frequencies within the range of 300 to 2,300 cycles per second are selected by the band filter BF-36 and are communicated by way of the low frequency hybrid coil LFH-2 and the artificial 115 line AL to the communicating conductors 175 and 176. Thence the voice currents pass by way of registering tip and ring contacts of answering jack AJ-11 and toll plug TP inserted therein to the connecting 120 cord circuit CC and the station 4 operator's telephone set associated therewith. A complementary path, which need not be traced in detail, is followed by the voice currents from the operator's transmitter at station 125 4 to the operator's receiver at station 1 by way of the transmitting branch of channel 4, station 4, the receiving branch of channel 4, group 1, at the switching station, the transmitting branch of channel 1, group 1, at the 130

switching station, and the receiving branch of channel 1 at station 1, carrier shifting modulations, as have been described, being effected at the switching station. When the 5 information incidental to the setting up of the connection has been communicated between the operators at the calling and called stations, the local lines at the two stations may be connected with each other through 10 the medium of the high frequency or carrier channels described, by the operator at each station inserting the local plug LP of the pair of connecting cords into the line spring-jack LJ of the local subscriber's line. Supervision of the local lines may be effected 15 in the usual way through the medium of the local supervisory lamps LSL under the control of the local supervisory relays 15.

If either operator wishes to signal the 20 other during the continuance of the connection she may do so by withdrawing the toll plug TP from and reinserting it in its associated channel springjack a number of times. Assuming that it is the operator at 25 station 1 who wishes to signal the operator at station 4, the withdrawal of the toll plug TP from the springjack CJ-41 in which it has been inserted opens the local contacts of springjack CJ-41 and thus breaks the energizing circuit of relay 54 (Fig. 3) normally 30 completed by way of conductor 74. The release of relay 54 withdraws the 225 cycle control frequency from the transmitting branch of the channel. At the same time the 35 circuit by way of conductor 77 including the toll supervisory lamp TSL and the winding of relay 50 (Fig. 3) is broken at the registering sleeve contacts of toll plug TP and springjack CJ-41. But relay 50 remains 40 operated as a result of the energizing circuit that is held closed, for it in the contacts of relay 64, which relay remains energized as long as the toll plug remains in the channel springjack at the distant station, station 4. 45 Therefore, relay 70 (Fig. 3) remains operated to maintain the energization of the transmitting branch of the channel and the application of the carrier frequency, and the busy lamps BL-1 of group 1 (Fig. 2) remain 50 lighted, but the withdrawal of the 225 cycle control frequency from the carrier wave transmitted from station 1 causes the disappearance of the control frequency at 55 called station 4 and the consequent deenergization of relay 161 (Fig. 12). When relay 161 releases its armature it breaks the normally closed shunt of the station 4 operator's toll supervisory lamp TSL, and this lamp consequently lights, and is lighted 60 and extinguished as many times as the operator at station 1 withdraws and reinserts the toll plug TP. The withdrawal of the 225 cycle control frequency from the carrier at 65 station 1 also has the effect of deenergizing relay 14 (Fig. 4) associated with channel 1

of group 1 at the switching station. But this is without effect, for the reason that as long as the connection between the two stations exists conductor 85 receives current for the energization of relay 1-4 of the blocking group over two paths, one of which is controlled by relay 14 of channel 1 responsive to the control frequency applied at the calling station and the other of which is controlled by relay 41 associated with channel 4 responsive to the control frequency applied at the called station. Therefore, when relay 14 is released by the withdrawal of the calling station control frequency relay 1-4 of the blocking group remains energized by way of the energizing path established through contacts of relay 41 held operated by the control frequency applied at the called station. Thus, the operator at either station may flash the supervisory lamp associated with the connecting cord circuit at the other station without causing the deenergization of relays 114 and 110 of channel 1 and relays 141 and 140 of channel 4 of switching group 1 over which the connection is assumed to be established, and the carrier shifting modulating frequencies therefore continue to be applied and the corresponding channels energized at the switching station. 90

When the conversation is ended and the toll plugs at both the calling and called stations are removed from the springjacks into which they have been inserted, relays 50, 60, 64, 54 and 70 (Fig. 3) are deenergized and released at the calling station, and also relays 51, 160, 161, 181 and 180 (Fig. 12) at the called station, and relays 14, 41, 1-4 114, 110, 141 and 140 (Fig. 4) at the switching station. The release of these relays restores all of the associated circuits to 100 their normal condition. 105

We will now assume that channel 4, representing station 4 in switching group 1 is in use at the time that the operator at station 1 inserts toll plug TP into springjack CJ-41 in attempting to establish communication with station 4 through the medium of group 1. In this case the application of the 225 cycle control frequency to the 23,333 cycle carrier of channel 1 at station 1 causes the operation of relay 14 associated with channel 1 of group 1 at the switching station (Fig. 4) in the same way as that which has previously been described. If channel 4 is at the time busy as a result 110 of being connected with channel 2, the relay 2-4 of the blocking group is in operated condition. If channel 4 is busy as a result of being connected with channel 3, relay 3-4 of the blocking group is in an operated condition. In either case the result of the operation of relay 14 when the station 1 operator attempts to extend the connection is to close a circuit that extends from battery through the winding of busy tone con- 120 125 130

trolling relay 10, armature and front contact of relay 14, conductor 85, and thence directly to ground either by way of the associated armature and front contact of relay 2-4 in the first case, or by way of the associated armature and front contact of relay 3-4 in the second case. In either case the direction connection of conductor 85 with ground, instead of by way of the resistance of the relay 1-4 of the blocking group, which would be the path closed if the channel of station 4 were not in use, permits a flow of current through the winding of relay 10 of sufficient volume to cause it to attract its armatures. Relay 10 in operating closes the circuit that extends from battery by way of the winding of relay 25 (Fig. 14), conductor 153, and left hand armature and front contact of relay 10 to ground. Relay 25 in operating applies current from the A battery for the energization of balanced modulator BM-4 and amplifier A-6 of the busy tone modulating apparatus; and the busy tone modulation of the 6,666, 10,000, 13,333 and 16,666 cycle frequencies is thereupon applied to conductors 151 and 152. At the same time relay 10 in attracting its right hand armatures breaks the continuity of the transmitting branch conductors of channel 1 and connects the outgoing ends of these conductors with the conductors 151 and 152 to which the busy tone modulation is being applied. As one of the busy tone modulations produced is that of the 6,666 cycle carrier, this modulation passes through the band filter BF-12 in the transmitting branch of channel 1 and is communicated over the channel paths already traced to the calling station where, after demodulation, the busy tone frequency is applied to the communicating conductors 75, 76, and thus to the operator's connecting cord circuit and the operator's telephone receiver. The source of busy tone employed for modulation in the balanced modulator BM-4 (Fig. 14) may be limited to a frequency or frequencies between 300 cycles and 2,300 cycles per second, so as to be excluded from the low pass filter LPF-1 associated with the control frequency receiving branches (Fig. 3) and to be diverted through the band filter BF-10 associated with the voice frequency circuit.

I may be seen from the foregoing that if the channel in the group representing the called station is in use the busy tone is instantly and automatically returned to the operator at the calling station. If the channel representing the called station is not in use, the channel matching modulating frequencies are immediately applied to the calling station channel and the called station channel to bring the two stations into communicating relation with each other. With busy test and connection extending circuits

such as those that have been described, the operator at the calling station may test the various switching groups represented at her station for an available channel to the called station as rapidly as she can insert the toll plug into and withdraw it from the series of calling springjacks in the horizontal row representing the called station. Whenever the operator inserts the toll plug into a station springjack and does not immediately hear the busy tone, she knows that the connection is already extended through to the called station. If, for instance, the station 4 channel in the switching group 1 is busy, the operator at station 1 hears the busy tone in her telephone immediately upon the insertion of toll plug TP into calling springjack CJ-41. Thereupon she withdraws the plug from calling springjack CJ-41 and inserts it into springjack CJ-42, the withdrawal of the plug from springjack CJ-41 instantly returning the associated circuits at both the calling station and the switching station to normal. The insertion of the toll plug into springjack CJ-42 energizes channel 2 at station 1 and applies the 225 cycle control frequency modulation. This causes the energization of the 225 cycle responsive relay associated with channel 2 of group 2 (Fig. 7); and immediately upon the operation of this relay either the extreme left hand relay of the six in the blocking group of Fig. 7 is energized to bring about the application of the 33,333 cycle modulating frequency to the receiving branch balanced modulators of channel 1 and channel 2 of switching group 2 to bring the corresponding channels into operative relation with each other, or the busy tone controlling relay associated with channel 2 of group 2 is operated, in case channel 1 is in use, to return the busy tone to the operator at calling station 1. Inasmuch as channel 2 represents station 1 and channel 1 represents station 4 in switching group 2 of Fig. 7, the operative interconnection of channel 2 with channel 1 results in the interconnection of station 1 with station 4 in exactly the same way as has heretofore been described in connection with the operation of the circuits associated with group 1. In like manner the insertion of the connecting circuit toll plug into springjack CJ-43 of station 1 (Fig. 2) either immediately returns a busy test to the station 1 operator or completes a connection between station 1 and station 4 by way of channels 3 and 2 of group 3 (Fig. 10); and similarly the insertion of the plug into calling springjack CJ-44 of station 1 immediately returns a busy test or completes the connection between station 1 and station 4 by way of channels 4 and 3 of group 4 (Fig. 13). The four calling springjacks CJ-21, CJ-22, CJ-23 and CJ-24 may be used in a

similar manner for testing and completing connection through the various switching groups when station 1 desires to test for an available channel and complete connection with station 2, and the calling spring-jacks CJ-31, CJ-32, CJ-33 and CJ-34 may similarly be used when station 1 desires to test for an available channel and complete connection with station 3. The procedure with respect to initiated and incoming calls to and from the various distant stations is the same at all of the other stations as that which has been described in connection with the call for station 4 as 10 sumed to originate at station 1, and will be understood without further description. In each case it is only necessary for the originating operator to insert the toll plug of a pair of connecting cords into a calling spring-jack representing the desired distant station the associated busy lamp of which is not lighted and from which a busy signal is not immediately returned; and for the operator in case of an incoming call merely 20 to insert the toll plug of a pair of connecting cords into an answering springjack associated with a lighted calling lamp.

Reference will now be made to the modified form of the system as illustrated in Figs. 17 and 18. In this modification the shifting of the carrier frequencies to effect the matching of the channels, and therefore the interconnection of the stations, is manually controlled by an operator at the switching center or station, instead of being under the control of the operators at the outlying stations as in the preferred form of the invention that has been described.

Figs. 17 and 18 show only enough of the modified organization to bring out the important points of difference between the modified form and the form previously described. The complete organization of the modified form may be produced merely by 40 extending the system in accordance with the disclosure of Figs. 17 and 18, with appropriate variations in the channel and line associations in the various switching groups, and supplementing the portion of the organization shown in these figures with the outlying or toll station circuits of the organization as it has already been described, with certain slight changes that will be indicated.

Fig. 17 illustrates diagrammatically the circuits of switching group 1 of the modified form, and Fig. 18 shows the portion of the switching operator's circuit common to all of the switching groups together with 50 the portion of the switching operator's circuit through which the operator exercises control over the channels of the switching group illustrated in Fig. 17. In the main, the circuits of group 1 shown in Fig. 17 are identical with the circuits of group 1

of the previously described form illustrated in Fig. 4. Inasmuch, however, as the feature of automatic interconnection of the channels under the control of the distant stations is not employed, the three relays of each channel that are selectively controlled from the associated remote stations are replaced by a single relay which serves merely to govern the operation of associated calling and supervisory signals at the switching stations, and the group of blocking relays shown at the top of Figs. 4, 7, 10 and 13 is omitted. Also, for the purpose of simplification the busy tone circuits and apparatus are dispensed with in the modified organization, the busy condition of the called channel of a group being indicated telephonically by the switching operator to the operator at the distant station.

The switching operator's position, as illustrated in Fig. 18, is provided with an answering key, AK-1, AK-2, AK-3 and AK-4, for each of the four channels of the switching group, and associated with each answering key is a calling lamp, L-1, L-2, L-3 and L-4, respectively. The calling lamp is lighted by an incoming call over the corresponding channel, and the circuit condition necessary for the answering of the call is established by pressing the associated 85 answering key. In addition, for each switching group the operator's position is provided with the six connecting keys CK-1 to CK-6, inclusive, and six corresponding supervisory keys SK-1 to SK-6, 90 inclusive. Each of the six sets of connecting keys and supervisory keys has associated with it a pair of supervisory lamps L-5 to L-16, inclusive, the two supervisory lamps of each pair indicating to the operator the condition of use or disuse at the distant station of the two channels that are interconnected by the pressing of the particular associated connecting key. Each switching group also is provided with four 100 pilot lamps, PL-1 to PL-4, inclusive, which are associated with the six sets of connecting keys and supervisory keys, and which by their illuminated or unilluminated condition indicate to the operator the busy or idle condition of each of the four channels of the particular switching group. The portion of the switching operator's circuit that is common to all of the switching groups includes the operator's transmitter T and the operator's receiver R, which are merely conventionally indicated, a key OK for applying a control frequency to the carrier of any of the channels with which the operator's circuit is connected, the necessary filters and modulating apparatus for effecting the selection and combination of the telephonic, controlling and carrier frequencies, and two groups of four relays each. The relays 211, 212, 213 and 214 of the 115 120 125 130

first group control the connection of the operator's common circuits with group 1, group 2, group 3 and group 4, respectively, and relays 221, 222, 223 and 224 of the 5 second group control the application of one or another of the four carrier frequencies 6,666, 10,000, 13,333 and 16,666, respectively, to the balanced modulator in the operator's transmitting circuit to determine the particular 10 one of the four channels with which the operator will be placed in operative relation.

The organization of the circuits will, it is thought, sufficiently appear in connection 15 with the following description of operation of the modified form of the system. It may be assumed that station 1 with which channel 1 of group 1 (Fig. 17) is associated is calling for connection with station 4 with 20 which channel 4 of group 1 is associated; and that station 1 in initiating the call has applied to channel 1 the 23,333 cycle carrier modulated with a control frequency of 150 25 cycles per second. The modulated lower side band of the 23,333 cycle carrier passes through band filter BF-41 in the receiving branch of channel 1 and is applied to the series input circuit of balanced modulator BM-6. The 23,333 cycle frequency is being simultaneously 30 applied to the parallel input circuit of balanced modulator BF-6 by way of high frequency hybrid coil HFH-10. Among the products of modulation of these frequencies that appear in the output circuit of the balanced modulator BM-6 is the reproduced 150 cycle control frequency applied at the distant toll station in initiating the call. This 150 cycle control frequency passes through the low pass filter 40 LPF-7, is amplified in amplifier A-8 and brings about the operation of relay 201, which relay is so constructed and adjusted, as has previously been described, as to be selectively responsive to this particular frequency. Relay 201 in operating closes a 45 circuit that extends from battery through a resistance 209, which may be of any desired appropriate value, armature and front contact of relay 201, conductor 251, armature and back contact of relay 291 and calling lamp L-1 to ground. This causes the illumination of lamp L-1, and the operator answers the call by pressing the associated answering key AK-1. This completes a 50 circuit that extends from battery through the winding of relay 205 (Fig. 17), conductor 261, and right hand switch spring and contact of answering key AK-1 to ground. Relay 205 in operating closes a 55 circuit that connects the receiving branch conductors of channel 1 with the operator's telephone receiver R by way of the branch of the common conductors 270 that extends to the front contacts of relay 205. Included 60 in the circuit thus completed is the band fil-

ter BF-49, which permits the passage of the currents in the voice frequency range reproduced by demodulation in the balanced modulator BM-6 and prevents the passage of the lower control frequency and the higher 70 frequency products of modulation. The switching station operator is thus placed in receiving relation with the operator at the distant station.

At the same time the pressing of answering key AK-1 in response to the lighting of calling lamp L-1 closes a circuit that extends from battery through the winding of relay 221 (Fig. 18), conductor 241, closed contacts of answering key AK-1, conductor 231, winding of relay 211, and winding of common relay 210 to ground. Relays 221, 211 and 210 are thus operated. Relay 221 in operating applies the 6,666 cycle frequency to the parallel input circuit of balanced modulator BM-7. The 6,666 cycle frequency is therefore modulated by the voice currents produced in the operator's transmitter T and applied to the series input circuit of balanced modulator BM-7 80 by way of band filter BF-52. The balanced modulator BM-7 and the balanced amplifier BA-7 have been made active through application of current from the A battery by the operation of relay 210: so 90 that the modulated 6,666 cycle produced in balanced modulator BM-7 passes by way of band filter BF-51 to balanced amplifier BA-7 where it is amplified and applied to conductors 271 by way of contacts of relay 211 closed when relay 211 was energized 100 by the pressing of answering key AK-1 as described. The conductors 271 extend to the common conductors 200 with which all of the receiving and transmitting channel 105 branches of group 1 are connected. As it is the modulated 6,666 cycle carrier that is being applied to the common conductors 200 as a result of the pressing of answering key AK-1, this modulated carrier is selectively 110 directed by way of band filter BF-42 of the channel 1 transmitting branch and high frequency hybrid coil HFH-11 to the line extending to the calling station. Therefore, by pressing answering key AK-1 the 115 switching station operator is placed in both receiving and transmitting telephonic relation with the operator at calling station 1.

It has been assumed that the operator at station 1 desires connection with station 4. 120 When this information has been received the switching station operator presses the appropriate one of the six connecting keys CK-1 to CK-6, inclusive. The particular two stations which each of the six keys is 125 adapted to interconnect is indicated by the reference characters associated with each key. In the present instance, as the two stations to be interconnected are station 1 and station 4, connecting key CK-5 is 130

operated. When the operator presses the key a circuit is completed that extends from battery in parallel branches one of which includes relays 340 and 341 (Fig. 17) and the other of which includes relays 310 and 314, thence by way of conductor 305 and the fifth or right hand set of contacts of connecting key CK-5 to ground. Relays 310 and 340 in operating apply current from the A battery for the energization of the respective balanced amplifiers BA-6 and BA-8 of the associated channels, channel 1 and channel 4. Relay 314 in operating applies the 40,000 cycle frequency by way of high frequency hybrid coil HFH-10 to the parallel input circuit of balanced modulator BM-6 of channel 1. The intermodulation of the 40,000 cycle frequency with the lower side band of the 23,333 cycle frequency is in accordance with what has already been described in connection with the operation of the other embodiment of the invention; and the resultant upper side band of the 16,666 cycle frequency passes through band filter BF-40 in the receiving branch of channel 1, is amplified in balanced amplifier BA-6, passes to the common conductors 200, and then is selectively directed by way of band filter BF-48 in the transmitting branch of channel 4 to the line extending to called station 4. Relay 341 in operating applies the 40,000 cycle frequency for the modulation of the lower side band of the 33,333 cycle carrier that is received by way of the band filter BF-47 of channel 4 as soon as the operator at called station 4 has responded to the incoming call. The intermodulation of the 33,333 cycle side band and the 40,000 cycle frequency in balanced modulator BM-8 of channel 4 produces the upper side band based on the 6,666 cycle frequency. This side band passes through band filter BF-53, is amplified in balanced amplifier BA-8, passes to the common conductors 200, and thence is selectively directed to the line extending to calling station 1 by way of the transmitting branch of channel 1 including band filter BF-42.

When the connecting key CK-5 is operated to establish operative relation between station 1 and station 4 as has been described, circuits are closed for the energization of relays 291 and 294 (Fig. 18) by way of conductors 285 and 288, respectively, and the third and fourth contacts from the left of the connecting key CK-5. Relays 291 and 294 in operating open at their back contacts the circuits for the energization of associated calling lamps L-1 and L-4, respectively, and close at their front contacts circuits for the energization of the two supervisory lamps L-13 and L-14 associated with connecting key CK-5, these circuits being by way of conductors 281 and

284 and the first and second contacts from the left of the connecting key CK-5. Under the conditions thus set up, as long as connection continues with channel 1 at calling station 1 the 150 cycle control frequency is applied to the carrier and keeps the relay 201 (Fig. 17) at the switching station energized; and the operation of relay 201 closes a circuit that extends from battery by way of resistance 209, closed contacts of relay 201, conductor 251, armature and front contact of relay 291, conductor 281, second contact from the left of connecting key CK-5, and supervisory lamp L-13 to ground. Similarly as long as the connection remains established at called station 4, the presence of the 150 cycle control frequency on the carrier holds energized the relay 204 (Fig. 17) at the switching station; and this completes a circuit that extends from battery through the resistance coil, closed contacts of relay 204, conductor 254, armature and front contact of relay 294, conductor 284, left hand contacts of connecting key CK-5, and supervisory lamp L-14 to ground. Therefore, the supervisory lamps L-13 and L-14 are under the control of the apparatus at the distant toll stations, being illuminated as long as the connection continues at the respective distant stations and being extinguished when the connection at the corresponding station is taken down. By an obvious rearrangement of the supervisory lamp circuits well known in the art the supervisory lamps could be made to be dark during the continuance of the connection and illuminated when the connection is disestablished at each end. In the present arrangement the darkening of the supervisory lamps L-13 and L-14 indicates to the switching operator the termination of the conversation, and she may then disconnect by merely returning connecting key CK-5 to normal.

If during the continuance of the connection it is necessary or desirable for the switching operator to listen in, she may do this by operating the associated supervisory key SK-5. When the supervisory key is pressed the relays 205 and 208 (Fig. 17) are energized by way of conductors 261 and 264, respectively, and the closed contacts of supervisory key SK-5. The relays 205 and 208 in operating establish connection by way of the respective band filters BF-49 and BF-54 between the incoming or receiving branches of channels 1 and 4, respectively, and the common conductors 270 extending to the switching operator's telephone receiver R. Consequently whatever voice frequencies are present in the receiving branches of channels 1 and 4 by reason of demodulation in balanced modulators BM-6 and BM-8, respectively, are permitted to pass by way

of band filters BF-49 and BF-54 to the switching operator's telephone receiver, and the switching operator is thus enabled to supervise the conversation. If during the 5 continuance of the connection it should be necessary for the switching operator to speak to one or the other or both of the interconnected parties or subscribers, this can be done by means of the answering keys AK-1 10 and AK-4. By pressing the answering key AK-1 the same condition with respect to the connection of the operator's transmitter with the channel circuits is re-established as was previously described in connection 15 with the answering of the call from station 1; that is relay 221 (Fig. 18) is energized to select the 6,666 cycle frequency for modulation by the voice currents from the operator's transmitter, relay 211 is operated 20 to apply the 6,666 cycle modulated carrier to the circuits of switching group 1, and at the same time relay 205 (Fig. 17) is operated to establish telephonic receiving relation between the switching operator's telephone receiver 25 and the receiving branch of channel 1. Therefore, the pressing of answering key AK-1 during the continuance of a connection permits the switching operator to converse with the subscriber or operator at station 1. Similarly the pressing of answering key AK-4 during the continuance of the connection permits the switching station operator to converse with the operator or subscriber at station 4.

30 If the switching station operator at any time desires to call the operator at one of the distant stations, she may do this by pressing the particular one of the answering keys AK-1 to AK-4, inclusive, that is associated 35 with the switching group channel that leads to the desired station, and at the same time pressing the calling key OK associated with the operator's telephone set. The pressing of the answering key establishes 40 transmitting and receiving relations between the switching operator and the channel associated with the depressed key, in the manner that has been described; and the pressing of the key OK applies the 150 45 cycle control frequency as a modulation of the carrier that is applied to the operator's balanced modulator BM-7. The presence of the 150 cycle control frequency in the carrier side band that is applied to the 50 switching station transmitting branch of the selected channel results in the operation of the control relay associated with the receiving branch of the channel at the distant station, and the lighting of the calling lamp 55 at that station. As a result the operator at the distant station makes connection with the channel identified by the lighted calling lamp and thus is brought into communicating relation with the operator at the switching 60 station.

The switching station operator is guided in completing connection between a calling channel and a called channel by the pilot lamps PL-1 to PL-4, inclusive, associated with the connecting and supervisory 70 keys and supervisory lamps of each switching group. These pilot lamps are associated respectively with the four channels of the corresponding group, and each lamp remains lighted as long as its associated 75 channel is in use. For instance, in the case that has been assumed in which connection is established between channels 1 and 4 of switching group 1, the pressing of connecting key CK-5 not only operates relays 291 80 and 294, but also closes energizing circuits that extend from battery through pilot lamps PL-1 and PL-4 by way of conductors 285 and 288, respectively, and the third and fourth contacts from the left of 85 key CK-5 to ground. Therefore, as long as key CK-5 remains operated to establish connection between channels 1 and 4, the associated pilot lamps PL-1 and PL-4 of 90 channels 1 and 4, respectively, remain lighted. If while this condition continues, either one of the two stations, station 1 and station 2, associated with the other two channels of the group should initiate a call 95 over this switching group for either station 1 associated with channel 1 or station 4 associated with channel 4, the switching station operator is immediately informed by the lighted condition of pilot lamps PL-1 and PL-4 that the corresponding channel and 100 station in this group is in use. Under these circumstances the switching operator may inform the calling operator that such is the case; and by glancing at the corresponding pilot lamps of the other switching groups on 105 her keyboard she may see that the desired connection may be established over another one of the switching groups and may so inform the calling operator at the distant station. The operator at the distant station thereupon establishes connection with the channel associated with the group at the distant station thus designated for connection, and the switching station operator may complete the connection by operating the appropriate connecting key in the designated 110 switching station group.

The toll or distant station circuits for co-operation with the circuits of Figs. 17 and 115 18 may be like the station circuits illustrated in Figs. 2, 5, 8 and 11 and in Figs. 3, 6, 9 and 12 excepting for the omission of certain of the elements which are present on account of the necessity in the first described modification for the transmission and reception of a plurality of control frequencies. This being the case it has not been thought necessary to burden the disclosure with a detailed description of the toll or distant 120 station circuits and apparatus employed in 130

the modification of Figs. 17 and 18. For use with the last described modification the toll station channel circuits as illustrated in Fig. 3, for instance, may be modified merely by omitting the receiving sub-branches that are selective of the 75 cycle and 225 cycle control frequencies together with the corresponding contacts of relay 50, and by the omission of the transmitting sub-branches that control the application of the 75 cycle and 225 cycle control frequencies, thus leaving in the circuit in each case merely the branch that has to do with the reception and transmission of the 150 cycle control frequency that has been arbitrarily chosen for use in the modified form. At the toll or distant station the switchboard circuit, as illustrated, for instance, in Fig. 2, all of the springjacks may be omitted with the exception of a single springjack for each of the four channels, and, if desired, one or more multiple springjacks at other operators' positions for each of the four channels. This is for the reason that the plurality of springjacks provided for each channel in the form of the invention illustrated in Fig. 2 are incident to the automatic selective transmitting and receiving features that are employed in the first described form of the invention. Inasmuch as the channel and station interconnection in the modified form is accomplished manually at the switching station, only those springjacks indicated in Fig. 2 need be retained that operate, when connection is made with them, to apply the 150 cycle control frequency to the carrier of the associated channel; and by locating in proximity to each of these channel terminating springjacks the calling lamp of the corresponding channel, and a busy lamp for each multiple springjack terminal in case there are a plurality of operators' positions at the toll station, the selective springjack terminals of the various channels as illustrated in Fig. 2 may be omitted. Such slight modifications in the circuit organization of the distant toll stations are obvious, and, it is thought, are within the skill of those ordinarily conversant with the art who may desire to practice the invention.

What is claimed is:

1. In a carrier wave communicating system, a plurality of carrier multiplex lines each having a plurality of channels, a switching station in which said lines converge, and means for selectively operatively interconnecting any two of said lines by shifting the frequency level of the chosen channel carrier side band transmitted from each line with a single frequency shifting operation.
2. In a carrier wave communicating system, a plurality of carrier multiplex lines each having a plurality of channels, a switching station in which said lines converge, and

means controlled from a distant point for selectively operatively interconnecting any two of said lines by shifting the frequency level of the chosen channel carrier side band transmitted from each line in a single frequency shifting operation. 70

3. In a carrier wave communicating system, a plurality of a carrier multiplex lines each having a plurality of channels, a switching station in which said lines converge, and means at said station for selectively operatively interconnecting any two of said lines by matching the carrier frequency of each interconnected line with the carrier frequency of the other interconnected line by shifting the frequency level of the chosen channel carrier side band transmitted from each line in a single frequency matching operation. 75

4. In a carrier wave communicating system, a plurality of carrier multiplex lines each having a plurality of channels having an incoming branch and an outgoing branch for each channel, a common outlet upon which an incoming branch of a channel from each line converges, and from which an outgoing branch of a channel to each line diverges, and frequency-changing means associated with each incoming branch for shifting the frequency of the carrier side band assigned to that branch in a single frequency shifting operation to cause it to pass through said common outlet and into a particular one of said outgoing branches diverging therefrom. 90

5. In a carrier wave communicating system, a plurality of carrier multiplex lines, a switching station in which said lines converge, a frequency selective network of local circuits at said switching station connecting an incoming channel branch from each line with an outgoing channel branch to each line, and wave modulating means in each incoming branch for selectively shifting the frequency of the incoming carrier side band in a single frequency shifting operation to predetermine the subsequent path of flow of the carrier through said frequency selective network. 105

6. In a carrier wave communicating system, a plurality of carrier multiplex lines each having a plurality of channels, a switching station in which said lines converge, and means for connecting an incoming channel to a desired outgoing channel by shifting the frequency of the incoming channel to that of the outgoing channel in a single frequency shifting operation. 115

7. The method of operatively interconnecting any two of a plurality of carrier multiplex lines each having a plurality of channels, which consists in selectively modulating the incoming carrier wave of a channel of each line by a wave of a frequency such as to shift the carrier frequency of each 120 125 130

line in a single frequency shifting operation by an amount sufficient to accommodate it to the frequency at which the channel of the other line of the pair desired to be interconnected is adapted to operate.

8. In a carrier wave communicating system, a plurality of carrier multiplex lines each having superposed thereon a plurality of channels equal in number to the number of lines and each channel having an incoming and outgoing branch, a switching station at which said lines converge, a frequency selective system of conductors and devices permanently connecting an incoming channel branch from each line with an outgoing channel branch to each line, and frequency-changing means for changing the frequency of the carrier side band of any incoming branch to predetermine its path of flow through said frequency selective system to any desired outgoing channel branch.

9. In a carrier wave communicating system, a plurality of carrier multiplex lines each having superposed thereon as many channels as there are lines, a switching station in which said lines converge, a common permanent connection between an incoming channel branch from each line and an outgoing channel branch to each line, and means for selectively shifting the frequency of the carrier side band of an incoming channel branch of any of said lines to direct said carrier side band to the outgoing channel branch of any desired one of said other lines.

10. In a carrier wave communicating system, a plurality of multiplex lines each having a plurality of channels comprising incoming and outgoing branches, a switching station, said channels being grouped at said station, a channel from each line appearing in each group, a common outlet for each group upon which an incoming branch of a channel from each line converges and from which an outgoing channel branch to each line diverges, and frequency changing means associated with each incoming branch for shifting the carrier side band frequency of that branch to cause it to pass through the associated common outlet and into a particular one of the outgoing branches diverging therefrom.

11. In a carrier wave communicating system, a plurality of carrier multiplex lines each having superposed thereon as many channels as there are lines, a switching station in which said lines converge, said channels being divided into groups at said station, a channel from each line appearing in each group, a common outlet for each group upon which an incoming branch of a channel from each line converges and from which an outgoing channel to each line diverges, frequency changing means associated with each incoming branch for shifting the car-

rier side band frequency of that branch to cause it to pass through the associated common outlet and into a particular one of the outgoing branches diverging therefrom.

12. In a carrier wave communicating system, a plurality of carrier multiplex lines, each having a plurality of channels comprising incoming and outgoing branches, calling and called stations for said lines, a switching station, a common outlet at said station upon which a branch incoming to said station from each line converges and from which a branch outgoing from said station to each line diverges, frequency changing means associated with each branch incoming to the station for shifting the carrier side band frequency of that branch to cause it to pass through the common outlet and into a particular one of the outgoing branches diverging therefrom, means at the calling station for controlling said frequency shifting means including means for applying a modulating wave to the incoming branch of a channel, and a calling signal for the selected outgoing branch at the called station responsive to said modulating wave.

13. In a carrier wave communicating system, a plurality of carrier multiplex lines, each having a plurality of channels comprising incoming and outgoing branches, calling and called stations for said lines, a switching station, a common outlet at said station upon which the branch incoming to the station from each line converges and from which channels from the stations to each line diverge, frequency changing means associated with each incoming branch for shifting the frequency of the carrier side band of that branch to cause it to pass through the common outlet and into a particular one of the outgoing branches diverging therefrom, means at the calling station for controlling said frequency shifting means by applying a modulating wave to the incoming branch of a channel, a supervisory signal at the calling station lighted when the call is initiated, a manual terminal at the called station for the selected outgoing branch, a calling signal associated therewith responsive to said modulating wave, means actuated in connecting with said manual terminal for extinguishing said calling signal and for applying a modulating wave of the transmitted carrier side band to the selected outgoing branch, and means responsive to said last mentioned modulating wave for extinguishing said supervisory signal.

14. In a carrier wave communicating system, a plurality of multiplex lines each having a plurality of channels comprising incoming and outgoing branches, a switching station, a common outlet at said station upon which a branch of a channel incoming to the station from each line converges and from

- which a branch outgoing from the station to each line diverges, frequency changing means associated with each incoming branch for shifting the frequency of the carrier side band of that branch to cause it to pass through the common outlet and into a particular one of the outgoing branches diverging therefrom, switching means for controlling said frequency changing means to interconnect a desired incoming and outgoing channel, and means operatively associated with said switching means and operating during the time a connection is established for marking the channels that are connected.
15. In a carrier wave communicating system, a plurality of multiplex lines each having a plurality of channels comprising incoming and outgoing branches, a switching station, a common outlet at said station upon which a branch of the channel incoming to said station from each line converges and from which a branch outgoing from said station to each line diverges, an answering lamp for each channel, means actuated when a channel is taken for use for lighting the corresponding lamp, frequency changing means associated with each incoming branch for shifting the carrier side band frequency of that branch to cause it to pass through the common outlet and into a particular one of the outgoing branches diverging therefrom, switching means at said switching station for controlling said frequency changing means to interconnect a desired incoming and outgoing channel, and busy signals operated by said switching means for indicating the condition of use of any of said channel branches.
16. In a carrier communicating system, a plurality of carrier multiplex lines, each having superposed thereon a plurality of carrier channels employing respectively different frequencies, normally inoperative interconnecting paths normally extending from the incoming channels of each line to given outgoing channels of the other lines, and means for establishing communicating relation between any two lines comprising means for rendering operative the interconnecting paths already existing between a particular pair of said channels, said last means comprising frequency-shifting apparatus for changing the frequency of the message waves transmitted over one channel of the pair to the frequency level which is individual to the other channel of the pair.
17. In a carrier wave intercommunicating system, a plurality of carrier multiplex lines each having superposed thereon a plurality of carrier wave channels employing respectively distinct carrier frequencies, a switching station and means at said station for selectively shifting the frequency of incoming carrier communicating waves by definite amounts, to produce resultant carrier wave frequencies to which predetermined channels of other lines are exclusively selective.
18. In a carrier wave communicating system, a plurality of carrier multiplex lines, a plurality of carrier wave channels superposed on each of said lines, the carrier channels on any line employing carrier frequencies differing respectively among themselves, and means controlled over any channel of a line for selecting and establishing operative connection to a channel of any other of said lines, the particular channel of the selected line to which connection is made being determined in each case by the particular channel on the initiating line over which the call is initiated.
19. In a carrier wave communicating system, a plurality of carrier channels superimposed upon each of said lines, the carrier channels on any line employing carrier frequencies differing respectively among themselves, connection identifying means associated with each channel, automatic connecting means for each channel controlled by the corresponding connection identifying means for selecting and extending an operated connection to a channel of the desired lines, said automatic connecting means acting in response to the control by a particular connection identifying means for determining the particular channel of the selected line to which the connection is to be extended.
20. In a carrier wave intercommunicating system, a plurality of multiplex carrier lines each having superposed thereon a plurality of carrier channels each of which employs a carrier wave of a distinctive frequency for transmission, means to directly repeat signal variations incoming on one channel of one line into an outgoing channel of another line, including means to shift the frequency level of said variations to accommodate the ranges employed by the channels to be interconnected, means to transmit control waves of different frequencies over a channel, and means dependent in its operation on the particular frequency of control wave that is transmitted for determining the extent by which the frequency level of the signaling variations is shifted.
21. A carrier interconnecting system for lines having a plurality of carrier channels of different frequency superposed on each line, comprising a number of switching groups, channel branches from different lines appearing in each group and being distributed among the lines, one channel per line, each such channel using a different carrier frequency from any of the others in the group, and means associated with each switching group to shift selectively the frequency of the waves incoming over a channel to the frequency level used by any desired outgoing channel appearing in that switching group, said means serving, by virtue of

the distribution of the channels appearing in that group among the lines, to select the outgoing line and to extend operative connection to a channel of said line.

5 22. An interconnecting system according to claim 21 in which the number of lines appearing in a switching station is equal to the number of channels on each line, and in

which there is a switching group for each set of channel terminals, taken one from each line and of respectively different frequency level. 10

In witness whereof, I hereunto subscribe my name this 8th day of March A. D. 1924.

EDWIN H. SMYTHE.
